WEFT SELECTING MECHANISM FOR WEAVING MACHINE

John Fisher and Nicholas P. Darash, Cleveland, Ohio, assignors to The Warner & Swasey Company, Cleveland, Ohio, a corporation of Ohio

Application May 29, 1956, Serial No. 588,060

39 Claims. (Cl. 139—125)

This invention relates to a weaving machine and more particularly to a filling or weft thread selecting mechanism for a weaving machine of the gripper shuttle type.

An object of the invention is to provide in a weaving machine of the gripper shuttle type improved and novel filling or weft thread selecting mechanism such that weft or filling threads of various colors or types can be selectively fed to and gripped by the shuttles and carried thereby through the shed to produce in the woven material predetermined designs or patterns.

Another object is to provide in a weaving machine of the gripper shuttle type weft thread selecting mechanism such that the weaving machine can be operated at efficient high speeds and will accurately produce the desired predetermined patterns or designs in the woven fabrics.

A further object is to provide in a weaving machine of the gripper shuttle type a weft thread selecting mechanism such as previously referred to and which mechanism is of such character that the weaving machine can be selectively employed to produce fabrics with or without designs or varying weft thread areas, thereby giving the machine great versatility as to the fabrics it is capable of weaving.

A further object is to provide a weaving machine of the gripper shuttle type having a weft thread selecting mechanism such that the machine has versatility in producing various types of fabric inasmuch as the weft or filling threads may be of a single color or type taken from a single package; or they may alternate as to color and type and be taken from two packages, or they may be formed of two colors or types taken from two packages and arranged in various desired orders or sequences, or they may consist of three or more different colors or types arranged in a consecutive and repetitious fashion, or they may consist of three or more colors or types arranged in a selective, non-consecutive fashion.

Further and additional objects and advantages of the invention not hereinbefore specified will become more apparent hereinafter during the detailed description of an embodiment of the invention which is to follow and which embodiment is illustrated in the accompanying drawings forming a part of this specification and wherein,

Fig. 1 is a front elevational view of a weaving machine of the gripper shuttle type having therein a filling or weft thread selecting mechanism embodying the present invention.

Fig. 2, Sheet 2, is a fragmentary plan view of the weaving machine shown in Fig. 1 and discloses the left-hand or picking side of the machine of Fig. 1.

Fig. 3, Sheet 3, is an end elevation view of the weaving machine taken approximately along line 3—3 of Fig. 2 looking in the direction of the arrows and with certain parts shown in section.

Fig. 4, Sheet 4, is a fragmentary vertical longitudinal section through the weaving machine and is taken approximately along lines 4—4 of Fig. 3 looking in the direction of the arrows.

2

Fig. 5, Sheet 5, is a developed view, partly in section and partly in elevation, and shows the gearing from the main drive shaft of the weaving machine to a cross shaft and to the upper cam shaft and from the cross shaft to the indexing cam in the indexer box.

Fig. 6, Sheet 6, is a detached end view of the indexer box looking from the left of Fig. 5 but turned 90° clockwise from normal horizontal position.

Fig. 7 is a horizontal longitudinal sectional view 10 through the indexer box and is taken substantially along line 7—7 of Fig. 6 looking in the direction of the arrows.

Fig. 8 is a vertical transverse sectional view through the indexer box and is taken along line 8—8 of Fig. 7 looking in the direction of the arrows but turned 90° clockwise from normal horizontal position.

Fig. 9, Sheet 5, is a longitudinal vertical sectional view through the indexer box and is taken substantially along line 9—9 of Fig. 7 looking in the direction of the arrows.

Fig. 10, Sheet 1, is a transverse vertical sectional view 20 similar to Fig. 8 but with the indexer box shown in normal horizontal position and showing a modified arrangement of locking mechanism for the index bar of the indexer box; said Fig. 10 being taken substantially along line 10—10 of Fig. 11 looking in the direction of the arrows.

Fig. 11 is a partial sectional and partial plan view, the section being taken substantially on line 11—11 of Fig. 10 looking in the direction of the arrows, a portion of the cover being broken away.

Fig. 12 is a fragmentary longitudinal vertical sectional 30 view taken through the indexer box substantially on line 12—12 of Fig. 10 looking in the direction of the arrows.

Fig. 13, Sheet 7, is a plan view of the feeder box, tensioner, filling detector mechanisms used in the weaving machine and forming part of the weft thread selecting 35 arrangement.

Fig. 14 is a side view of the feeder box mechanism shown in Fig. 13, partly in elevation and partially in section, and shows a filling thread feeding and gripper assembly in "index" position prior to moving horizontally 40 and longitudinally to "transfer" and "pick-up" positions.

Fig. 15, Sheet 4, is a fragmentary view similar to a portion of Fig. 14, partly in section and partly in side elevation and shows the filling thread feeding and gripper assembly in "transfer" to shuttle position.

Fig. 16, Sheet 4, is a fragmentary view similar to Figs. 44 and 15, and shows the filling thread feeding and gripper assembly in "pick-up" position.

Fig. 17, Sheet 8, is a vertical sectional view through the feeder box and the lock or restraining members for 50 the inactive filling thread feeding and gripper assemblies and is taken along line 17—17 of Fig. 13 looking in the direction of the arrows.

Fig. 18 is a vertical sectional view taken substantially on line 18—18 of Fig. 14 looking in the direction of the arrows.

Fig. 19, Sheet 9, is an end view of the feeder box taken approximately from line 19—19 of Fig. 14 looking in the direction of the arrows and showing also the weft thread detector feeler.

Fig. 20, Sheet 8, is a sectional view showing the drive from the upper cam shaft to the filling thread feeding and gripper assembly that is currently in position to be moved longitudinally in a feeding direction.

Fig. 21 is a detail plan view of the feeder arm and is 65 taken approximately from line 21—21 of Fig. 20 looking in the direction of the arrows and shows a safety release device mounted on said arm.

Fig. 22, Sheet 9, is a fragmentary plan view of that 70 end of the shuttle feeder mechanism adjacent to the thread tensioners and illustrates the latter.

Fig. 23 is a side elevational view of the thread tensioner

mechanism and the drive thereto which embodies a safety release; all four of the tensioning rods or needles of the tensioning mechanism being shown by full lines in raised position, with one of the same also being indicated in broken lines in the lowered position it occupies while its filling thread is being carried through the shed by the shuttle.

Fig. 24, Sheet 10, is an elevational view of the thread tensioner mechanism looking at the same from a position 90° removed from that in Fig. 23.

Figs. 25 and 26, Sheet 9, are detail horizontal sectional views taken respectively along lines 25—25 and 26—26 of Fig. 24 looking in the direction of the arrows; Fig. 26 illustrating the relationship of the parts when the tensioning arm or lever and the parts operatively connected to the free end thereof have moved downwardly from the plane of line 25—25 to the plane of line 26—26.

Fig. 27, Sheet 10, is a detached view partly in section and showing the shoe on the lower end of one of the thread tensioner rods, said rod in this view being arranged horizontally although in the machine it extends vertically.

Fig. 28 is an end elevational view of the drive for the thread tensioner and thread brake mechanisms.

Fig. 29 is a horizontal longitudinal sectional view taken along line 29—29 of Fig. 28 looking in the direction of the arrows and showing the cams for driving the thread tensioner and thread brake mechanisms.

Fig. 30 is a sectional view taken in the plane of line 30—30 of Fig. 28 looking in the direction of the arrows and showing the cam followers for actuating the thread tensioner arm shown in Fig. 23.

Fig. 31, Sheet 11, is a front view mostly in elevation of a different or stationary form of thread tensioning mechanism from that previously shown.

Fig. 32 is a vertical section taken substantially on line 32—32 of Fig. 31 looking in the direction of the arrows.

Fig. 33 is a horizontal sectional view taken substantially on line 33—33 of Fig. 31 looking in the direction of the arrows.

Fig. 34 is a vertical sectional view taken substantially on line 34—34 of Fig. 32 looking in the direction of the arrows.

Fig. 35, Sheet 12, is a plan view of the brake and drag mechanisms for the weft threads.

Fig. 36 is an end view of the brake and drag mechanisms shown in Fig. 35.

Fig. 37, Sheet 13, is an irregular sectional view taken approximately on the planes of and along line 37—37 of Fig. 36 looking in the direction of the arrows.

Fig. 38, Sheet 13, is a side view of the mechanism shown in Figs. 35 and 36 and is taken looking from the left-hand side of Fig. 36.

Fig. 39 is a partial sectional view with certain parts omitted and is taken substantially along line 39—39 of Fig. 38 looking in the direction of the arrows.

Fig. 40 is a vertical sectional view taken substantially along line 40—40 of Fig. 39 looking in the direction of the arrows.

Fig. 41, Sheet 14, is a view partially in section and partially in elevation illustrating the drive to the movable stop for the "transfer" position of the feeder.

Fig. 42, Sheet 15, is a view similar to a portion of Fig. 2 but on a larger scale.

Fig. 43, Sheet 14, is an isometric view on a larger scale of the indexing cam.

Fig. 44, Sheet 16, is a detached partial side elevational and partial vertical sectional view of the "pick back" safety device.

Fig. 45 is a plan view of the "pick back" safety device with the control shaft therefor shown in section, and

Fig. 46 is a partial sectional and partial elevational view of the "pick back" safety device taken looking from a location 90° from that of Fig. 44.

In Fig. 1 there is illustrated in front elevation a gripper shuttle type weaving machine in which the present invention

is embodied. The weaving machine illustrated comprises a supporting frame which includes a pair of side plates 50 and 51 secured to cross members, one of which is indicated at 52. The roll of cloth or fabric woven by the machine is indicated at 53 as wound upon the cloth beam 54. As is usual in this type of weaving machine it is provided with heddle frames 55 carrying heddles while the mechanism for actuating the heddles to form the shed is enclosed in the housing 56 as will be understood in the art.

The weaving machine has a main drive motor 57 which drives the main shaft 58 through a suitable drive such as a belt or chain 59. The main shaft 58 is provided with a hand wheel 60 and an automatically operating clutch and brake mechanism is enclosed within the housing 61 and functions in conjunction with mechanism causing rapid stoppage of the operating parts of the weaving machine in case of thread breakage or the breakage of some operative part of the machine all as will be known to those skilled in the weaving machine art.

At the left of the machine as viewed in Fig. 1, there is a picker box 62 while at the right of the machine is the receiving box 63. One of a multiplicity of spools or packages for the weft or filling threads is indicated at 64, but as shown in Fig. 2 there are four such packages or spools 64 in the present embodiment.

Only a brief summary of a weaving machine of the grip shuttle type need be set forth herein, inasmuch as the general features of such a machine are known by those skilled in the art and are described in such United States patents as Rossman, No. 2,099,627, Rusnov, No. 2,538,630, Farrwaller, No. 2,528,798 and Darash Nos. 2,654,397 and 2,660,201.

It will be understood that the weaving machine shown in Fig. 1 includes a warp beam which has wound upon it the warp threads. These threads pass over a whip roll and through a drop wire detector mechanism and the heddles of the heddle frames 55. The warp threads then pass from the heddles through a beat up reed and after leaving the reed the warp threads with the weft threads, later to be referred to, woven therein form the woven cloth C and the cloth passes over and around suitable take-up rolls and is wound upon the cloth beam 54 as indicated at 53. The reed is fastened to a lay bar which is operatively associated also with shuttle guides. The lay bar and shuttle guides are carried by a member or arm which in turn is carried and actuated by a lay bar shaft such that the shuttle guides enter the shed at the proper time for the firing therethrough of the successive shuttles and then leave the shed after the shuttles have been received in the receiving box 63 while the reed acts to beat up the weft threads carried through the shed by the shuttles. The shed is formed by the heddles in the heddle frames acting to raise certain of the warp threads and lower others thereof with the mechanism for actuating the heddles being in the housing 56 for the shedding mechanism as previously referred to. The weft threads are carried from the weft thread supply 64 through the shed by the shuttles which grip the weft threads and are fired from a picking mechanism in the picking box 62 to the receiving box 63.

It is not believed to be necessary to explain in greater detail the general elements of the weaving machine of the gripper shuttle type or their method of operation since the same are well known in the art and are described in the patents hereinbefore referred to.

Insofar as the firing of the individual shuttles in succession through the shed, the operation of the heddles to form the shed, the beating up of the weft threads and the return of the shuttles from the receiving box to the picking side of the machine are concerned, the weaving machine may be considered as conventional for the purposes of this description.

The present invention contemplates the provision of a mechanism for selectively and in predetermined arrange-

ment feeding weft threads from a multiplicity of stationary weft packages or spools to be transferred to and gripped by the successive shuttles before they are fired and thus to produce in the woven cloth or fabric predetermined designs or arrangements of weft threads.

The weft threads may be of different types or of different colors as desired, although of course a weaving machine equipped with the weft thread selecting mechanism embodying the present invention can be utilized for weft threads of the same type or color if it is so desired and this is advantageous in that it would produce an averaging of the weft threads to compensate for slight variations in thread thickness or color shade. Also there may be instances where it is desirable that the weft threads for a portion of the fabric all be of one type or one color and the selecting mechanism of the present invention is such as will take care of the situation just referred to. Consequently the weft selecting mechanism embodying the invention is versatile in that it is universal in its adaptation for the weaving of various types of fabric.

The weft selecting mechanism embodying the invention includes an indexer mechanism which is automatically indexed to control the selective feeding of the various weft threads from the packages to the shuttles in accordance with the particular design to be woven in the cloth.

The mechanism also includes arrangements for selectively tensioning the weft threads and for selectively operating drag and brake elements to function on the weft threads in conformity with the order in which the threads are fed and transferred to the shuttles.

In addition, the mechanism includes a common detector means for all of the weft threads but which means only detects one thread at a time, i.e., the particular weft thread that is being gripped and carried through the shed by the shuttle. The detector referred to will be understood as functioning for the purpose of instantly and automatically stopping the operation of the weaving machine should the particular thread that is being fired through the shed be improperly fed or becomes broken before its gripping shuttle has reached the receiving box or for some other cause the weft thread is not present to be contacted by the detector.

Referring now to Fig. 2 which is a plan view of the picking end of the weaving machine at which the weft selecting mechanism of the present invention is located, the indexer is indicated at I and is operatively connected to the indexable feeder box F. The weft or filing thread tensioner means is indicated at T and the drag and brake mechanism at B. The pattern or selecting mechanism is indicated at P while the picking box and the stationary packages or spools of the weft threads have been previously designated, respectively, by the reference numerals 62 and 64. The weft detector mechanism is indicated at D.

It will be understood that the elements I, F, D, T, B and P, as well as the picking mechanism in the picking box 62 are all driven from the main drive shaft 58 shown in Figs. 1 and 5.

Referring to Fig. 5, it will be seen that the main drive shaft 58 has fixed thereto a miter gear 65 which constantly meshes with a miter gear 66 fixed on a cross shaft 67 perpendicular to the main drive shaft 58 and rotatably supported in suitable bearings in the frame of the weaving machine.

Indexer

The shaft 67 has fixed thereto a spur gear 68 that constantly meshes with an idler gear 69 suitably supported in the machine and constantly meshing with a spur gear 70 that is fixed on the horizontally extending cam carrying shaft 71 of the indexer, see Figs. 5 and 7. The shaft 71 is rotatably supported in suitable bearings carried by the housing or box of the indexer I.

The indexing cam 72 is carried by the shaft 71 and is freely rotatable on said shaft. The indexing cam 72

in cross section is of the configuration shown in Fig. 8 and at its right-hand end as viewed in Fig. 7 it is provided with a counterbore 73. A hardened clutch plate member 74 is secured to the indexing cam 72 at the inner end of the counterbore 73. A clutch member 75 is provided with a sleeve portion that is splined on a reduced portion of the shaft 71 so that said member can move axially of the shaft but will rotate therewith.

The clutch members 74 and 75 are provided with inter-engaging clutch teeth and in effect constitute a single tooth clutch. However, in order that the clutch can sustain the torque load said clutch members 74 and 75 are each provided with more than one clutch tooth. Also the clutch members preferably are each provided with 15 diametrically opposed arcuate series of clutch teeth with the number of teeth in one of the series on each clutch member differing from the number of teeth in the other series thereon.

The purpose of the arrangement just referred to is 20 so that the full and proper engagement of the clutch members will only take place when the parts are in the same predetermined relationship to one another and hence the indexing cam 72 will be correctly disposed relative to the parts with which it cooperates.

25 The clutch member 75 is constantly urged toward the clutch member 74 under spring load by means of the coil spring 77 that surrounds the sleeve or hub of the clutch member 75 and at one end abuts against said clutch member and at its opposite end abuts against a 30 collar 78 secured to the shaft 71.

It will be seen that when the shaft 71 is being rotatably driven and when the teeth 76 of the clutch members 74 and 75 are engaged correctly that the indexing cam 72 will rotate with the shaft 71.

35 The indexing cam 72 adjacent the right-hand end thereof as viewed in Fig. 7 and within the counterbore 73 slidably mounts a spring-pressed plunger 79 which in its most inward spring pressed position has its inner end slightly spaced from the surface of a plunger engaging element 80 secured to the flange of the clutch member and having a surface area so dimensioned that it can engage the inner end of the plunger only during a predetermined angular portion of each complete rotation of the indexing cam 72. The plunger 79 is part 40 of a safety arrangement such that should the rotation of the indexing cam 72 be stopped during said predetermined angular portion of its rotation the clutch teeth 76 will ride out of engagement and the clutch member 75 will move to the right, as viewed in Fig. 7, against 45 the action of the spring 77, and then said plunger 79 would be moved by the element 80 toward the right against the action of its spring and an arm 81 secured to the right-hand end of the plunger 79 would actuate a 50 slidable pin member 82 carried by the housing of the 55 indexer I, see Fig. 9.

The slidable pin member 82 is operatively connected with suitable mechanism to actuate, when it is moved by the arm 81, the master stop rod 81a (see Figs. 2 and 3) of the weaving machine to disengage the main clutch 60 and actuate the brake mechanism contained in the housing 61 to stop the main shaft 58 as will be well understood.

65 Referring to Fig. 42 (Sheet 15), it will be seen that the indexing cam 72 is provided with a plurality of axially spaced peripheral grooves, there being four such grooves illustrated in the present embodiment, although it will be understood that the number of grooves may vary depending upon the number of weft threads of different type or color which the machine is capable of 70 selectively picking through the shed.

The grooves referred to extend partially around the periphery of the indexing cam 72 and each has a narrow straight walled portion 83 adjacent one of its ends and a wide straight walled portion 84 adjacent its opposite end. The lengths of the groove portions 83 and 84 are

correlated to a predetermined angular portion of a complete rotation of the indexing cam 72.

The inner ends of the wide straight walled portions 84 of the respective grooves are interconnected to the inner ends of the narrow straight walled portions 83 thereof by funnel-like portions 85, 85a, 85b and 85c reading from left to right of Fig. 42 and the lengths of said funnel-like portions are correlated to a predetermined angular portion of a complete rotation of the indexing cam 72.

The funnel-like portion 85 of the most left-hand groove as viewed in Fig. 42 has on its left side a straight wall and on its right side an inclined wall 86. The funnel-like portion 85a of the adjacent cam groove is provided on its left and right-hand sides, respectively, with inclined walls 87 and 87a while the portion 85b of the next cam groove toward the right has on its left and right-hand sides, respectively, inclined side walls 88 and 88a. The funnel-like portion 85c of the most right-hand cam groove as viewed in Fig. 42 has a straight right right-hand side wall and an inclined left-hand side wall 89. The purpose of the inclined side walls 86, 87, 87a, 88, 88a, and 89 of the funnel-like portions 85, 85a, 85b and 85c of the cam grooves in the indexing cam 72 will be pointed out hereinafter as will also the relative lengths of said inclined walls.

The housing for the indexer I slidably mounts an indexer bar 90 alongside the shaft 71 and parallel thereto but spaced therefrom. The indexer bar as shown herein is square or rectangular in cross section but it could be circular or of other shape and is slidably supported in suitable bearing bushings carried by the housing of the indexer I and located adjacent the opposite ends of the indexer bar.

At the right-hand side of the indexer housing as viewed in Figs. 7 or 42 the indexer bar projects outwardly of the housing for a purpose later to be explained. The indexer bar 90 mounts for horizontal sliding movement therethrough in opposite directions a multiplicity of cam follower pins spaced longitudinally of the indexer bar 90 and in Figs. 7 and 42 indicated by the reference numerals 91, 92, 93 and 94 reading from left to right.

Each of the cam follower pins laterally and outwardly of the indexer bar 90 mounts a coil spring 95, one end of which engages the indexer bar and the other end of which engages a collar on the outer end of the pin. These springs 95 normally maintain the pins in retracted position wherein their inner ends adjacent to the indexing cam 72 are flush with the surface of the indexer bar 90 and are inactive with respect to the indexing cam. The cam follower pins 91, 92, 93 and 94 have their outer ends that are remote to the indexing cam 72 engaging the enlarged heads on the inner ends of slidably plungers 96 that are carried by and project outwardly of the indexer housing I. The side of the indexer housing I is provided with a pair of vertically spaced parallel elongated supporting flanges or bosses 97 which mount therebetween four vertically extending supporting rods 98 spaced apart from left to right of the indexer housing as viewed in Fig. 7.

The supporting rods 98 rockably mount between the flanges 97 elongated vertically extending sleeves 99 which have adjacent their upper ends integral radially projecting arms 100 and adjacent their lower ends integral laterally projecting arms 101. The arms 101 extend past the outer ends of the plungers 96 and are provided with adjustable contact pins 102 that engage the outer ends of the plungers 96.

It will be seen that when the arms 100 of the sleeves 99 are moved in one direction i.e., a clockwise direction as viewed in Fig. 7, the adjustable contact pins 102 will push the plungers 96 inwardly of the housing with a resultant inward movement of the cam follower

pins 91, 92, 93 and 94 against the action of the springs 95.

During the operation of the weaving machine the arms 100 will be selectively moved at predetermined times to effect selective movement of the plungers 96 and of the cam follower pins 91, 92, 93 and 94 inwardly against the action of the springs 95. The mechanism for so selectively moving the arms 100 of the sleeves 99 will be described hereinafter.

10 The selective inward movement of the cam follower pins 91, 92, 93 and 94, as just referred to, functions during the operation of the machine to effect selective longitudinal indexing of the indexer bar 90 one, two or three steps to the right or to the left to any one of four indexed positions. The wide portions 84 of the cam grooves on the periphery of the indexing cam 72 are of such width that the inner ends of the cam follower pins 91, 92, 93 and 94 will always be located, regardless of the previous indexed position of the indexer bar 90, to enter such wide portions 84 of the cam grooves as the indexing cam revolves if projected inwardly against the action of the springs 95.

15 The inclined wall 86 of the most left-hand groove in the indexing cam 72 when engaged for its entire length by the inner end of the cam follower pin 91 during rotation of the indexing cam will effect maximum three step to the left longitudinal indexing movement of the indexer bar 90. When the inclined wall 86 is engaged by the inner end of the cam follower pin 91 for only two-thirds of its length it will effect two step to the left longitudinal indexing movement of the indexer bar 90. When the inclined wall 86 is engaged by the inner end of the cam follower pin 91 for only the last third of its length it will effect one step to the left longitudinal indexing movement of the indexer bar 90.

20 The engagement of the inclined wall 87 of the second from the left groove in the indexing cam 72 by the inner end of the cam follower pin 92 will effect one step to the right longitudinal indexing movement of the indexer bar 90. The inclined wall 87a of this groove when engaged by the inner end of the pin 92 for its entire length will effect longitudinal indexing two steps to the left and when engaged by the inner end of the pin 92 for the last half of its length will effect one step indexing to the left.

25 The engagement of the inclined wall 88 of the second from the right cam groove in the indexing cam 72 it will effect right-hand indexing of the indexer bar 90 two steps if the engagement is throughout the full length of the wall 88 and one step if the engagement occurs only during the last half of the length of the wall 88. When the inner end of the indexer pin 93 engages the inclined wall 88a of this groove it will effect one step indexing movement toward the left.

30 When the inner end of the cam follower pin 94 engages the inclined wall 89 of the most right-hand groove in the indexing cam 72 and for the full length of said wall three step right-hand indexing movement will be imparted to the indexer bar 90. When the inner end of the pin 94 engages the wall 89 for only the last two-thirds of its length a two step right-hand indexing movement of the bar 90 will result and if such engagement is only for the last third of the length of the wall 89 then one step right-hand indexing movement will occur.

35 It will be understood that the cam grooves in the indexing cam 72 only extend partially around the periphery of the indexing cam and that the period in which the inner ends of the cam follower pins are selectively in engagement with the inclined walls of the funnel-like portions of the cam grooves represents only a portion of a complete revolution of the indexing cam and this portion constitutes the indexing portion of each complete revolution of the indexing cam.

40 It will be understood that when the inner ends of the

cam follower pins 91, 92, 93 and 94 reach the narrow ends of the funnel-like portions of the cam grooves said pins are in position to pass into the narrow straight wall portions 83 of the cam grooves. It will also be understood that whenever one of the cam follower pins 91, 92, 93 and 94 is selectively pushed inwardly to engage in its cooperating cam groove it will only be held in its inwardly pressed position a time period correlated to a partial revolution of the indexing cam and including the indexing portion thereof, after which the spring 95 can move the pin to its retracted or outer position and also can move its associated plunger 96 to its outermost position with a consequent rocking of the sleeve 99 and arms 101 and 100 of said sleeve. The time period in which the cam follower pins are selectively moved to and held in their innermost position is controlled by the selecting mechanism hereinafter described.

It will be clear that the indexer bar 90 in the present embodiment of the invention can be indexed longitudinally right and left to any one of four indexed positions. It is necessary to provide means to lock the indexer bar 90 in its longitudinally indexed positions and to unlock the same so it can move longitudinally during each time period it is being indexed. The indexer bar 90 adjacent its left-hand end as viewed in Fig. 7 is provided with four locking grooves 103, 103a, 103b and 103c reading from right to left and spaced apart longitudinally of the indexer bar a distance equal to one step of indexing movement.

The indexing cam 72 has secured to its left-hand end as viewed in Fig. 7 a locking disk 104 which rotates with the indexing cam and shaft 71. The locking disk 104 is provided on its circumference with an arcuate cutaway recess 105 of an angular extent corresponding to the angular portion in each rotation of the indexing cam that the cam follower pins 91, 92, 93 and 94 will be in contact with the inclined side camming walls of the funnel-like portions of the camming grooves, that is, during the indexing portion of each rotation and the time that the indexer bar 90 is being longitudinally indexed.

The recess 105 is so located and the parts are so relatively timed that during the indexing of the cam follower bar the recess 105 will overlie the left-hand end of the cam follower bar 90 and the same will be free for indexing movement to the right or to the left as the case may be. However, as the locking disk 104 continues to rotate with the indexing cam 72 the recess 105 of the locking disk will move away from the indexer bar and said disk will pass into the locking groove that currently is aligned with the disk and thus the locking disk will lock the indexer bar 90 against any longitudinal movement during each non-indexing portion of the rotation of the indexing cam 72.

The indexer bar 90 is in indexed positions Nos. 1, 2, 3 and 4, respectively, when the locking disk 104 is in engagement with locking grooves 103, 103a, 103b, 103c. The cam follower pins 91, 92, 93 and 94 can be selectively inserted into their cooperating grooves in the indexing cam 72 to obtain, respectively indexed positions Nos. 1, 2, 3 and 4 of the indexer bar 90.

Assuming that the indexer bar 90 is in indexed position No. 1 as shown in Fig. 7, i.e., its most left-hand indexed position, and the pin 91 has been retracted by the spring 95 and it is desired to move the indexer bar 90 to indexed position No. 2, then the cam follower pin 92 is inserted into its groove and the engagement between the pin's inner end and the inclined wall 87 will effect a one step right-hand indexing movement to the bar 90 to indexed position No. 2.

Now if it is desired to index the bar 90 from indexed position No. 2 to indexed position No. 3 and the pin 92 is retracted and the pin 93 inserted into its groove, then the inner end of the pin 93 will contact the inclined wall 88 for the last half of its length as the indexing cam 72 rotates in the indexing portion of its rotation and this will effect a one step indexing movement of

the bar 90 to the right, i.e., to indexed position No. 3. Now assuming it is desired to index the bar 90 to its most right-hand or No. 4 indexed position and the pin 93 is retracted from its groove and the pin 94 inserted in its groove, then the inner end of the pin 94 will engage the inclined wall 89 for the last third of its length as the cam 72 rotates during the indexing portion and this will effect a one step indexing movement of the bar 90 to the right or to No. 4 indexed position.

- 10 Now assuming that the indexer bar 90 is in its most right-hand or No. 4 indexed position and it is desired to index it to No. 3 position and the pin 94 has been retracted from its groove and the pin 93 inserted in its groove, the inner end of the pin 93 engages the inclined wall 88a for its entire length and a one step indexing movement to the left to position No. 3 is effected.

Assuming now that it is desired to index the bar 90 from position No. 3 to position No. 2 and the pin 93 has been retracted from its groove, insertion of the pin 92 into its groove will cause the inner end of the pin 92 as the cam 72 rotates to contact the inclined wall 87a for the last half of its length and this will effect a one step left-hand indexing of the bar 90 to No. 2 indexed position.

- 20 25 Now assuming that pin 92 has been retracted and it is desired to index the bar 90 to No. 1 position then the pin 91 is inserted into its groove and the inner end of said pin will contact the last third of the length of the inclined wall 86 as the cam 72 rotates and this will effect one step indexing to the left of the indexer bar 90 to indexed position No. 1.

Now assuming that the bar 90 is in indexed position No. 1, i.e., its most left-hand indexed position, and it is desired to index it to indexed position No. 4, i.e., its most right-hand indexed position, and the pin 91 has been retracted from its groove and the pin 94 inserted into its groove, the inner end of the pin 94 will engage the inclined wall 89 for its full length and a three step right-hand longitudinal indexing movement will be imparted to the indexer bar 90 to move the same to its most right-hand or No. 4 indexed position.

- 30 35 40 Now assuming that it is desired to index the bar 90 from No. 4 position to No. 2 position and that the pin 94 has been retracted and the pin 92 inserted in its groove, then the inner end of the pin 92 will engage the wall 87a for its full length as the cam 72 rotates and this will effect a two step left-hand indexing movement of the bar 90 from indexed position No. 4 to indexed position No. 2.

- 45 50 55 Now assuming that the bar 90 is in indexed position No. 1 and it is desired to index it to position No. 3 then the insertion of the pin 93 into its groove will cause the inner end of the pin to engage the full length of the inclined wall 88 as the cam 72 rotates and this will effect a two step right-hand indexing movement to the bar 90 from indexed position No. 1 to indexed position No. 3.

Now assuming that the bar 90 is in indexed position No. 3 and the pin 93 has been retracted and it is desired to index the bar 90 to position No. 1, then the insertion of the pin 91 into its groove results in the inner end of the pin 91 contacting the inclined wall 86 for the last two-thirds of its length as the cam 72 rotates and this will effect a two step left-hand indexing movement to the bar 90 from position No. 3 to position No. 1.

- 60 65 70 75 Now assuming that the indexer bar 90 is in its indexed position No. 2 and it is desired to index it to position No. 4, then insertion of the pin 94 in its groove causes the inner end of the pin to engage the last two-thirds of the length of the inclined wall 89 as the cam 72 rotates and this effects a right-hand two step indexing movement of the indexer bar 90 to No. 4 indexed position.

It will be understood that the selective insertion of the pins 91, 92, 93 and 94 into their cooperating grooves in the indexing cam 72 will produce, respectively, indexing of the bar 90 to indexed positions Nos. 1, 2, 3 or

4 from whatever previous and different indexed position the bar may have occupied. It will also be understood that engagement of the inclined walls 86 and 89 of the most left-hand and the most right-hand grooves by the inner ends of their cooperating cam follower pins 91 and 94 will produce either one, two or three step indexing movement to the left or right, respectively, depending upon the point in the length of the walls 86, 89 at which the inner ends of the pins 91 and 94 engage therewith as the cam 72 rotates.

Similarly, the inclined walls 87a and 88 can be engaged by the inner ends of the pins 92 and 93, respectively, to effect one or two step left or right-hand indexing movement of the bar 90, respectively, depending upon whether the inner ends of said pins engage these walls throughout their full length or for only one-half of their length as the cam 72 rotates.

It will also be understood that only one of the cam follower pins 91, 92, 93 and 94 is inserted in a groove of the indexing cam 72 at any one time. Likewise, it will be understood that the locking disk 104 during the indexing portion in the cycle of operation when the pins are in the funnel-like portions of their respective slots will be so positioned that the cutout recess 105 straddles the bar 90 and the latter is free to have indexing movement imparted thereto while at all other times the locking cam 104 will extend into one of the locking slots or grooves 103, 103a, 103b and 103c to lock the bar against movement when it is in indexed positions Nos. 1, 2, 3 and 4.

In Figs. 10, 11 and 12, sheet 1, a modified arrangement for locking the indexer bar 90 in indexed positions Nos. 1, 2, 3 and 4 from that just described is illustrated. In this modified arrangement the left-hand end of the indexer bar 90, as viewed in the drawings, is provided with four longitudinally spaced locking grooves 106, 106a, 106b and 106c differing in cross sectional configuration from the locking grooves 103, 103a, 103b and 103c to the extent that the tapered locking end of a lock plunger 107 will interfit therewith. The grooves 106, 106a, 106b and 106c correspond, respectively, to indexed positions Nos. 1, 2, 3 and 4 of the indexer bar 90.

The lock plunger 107 is slidably adjacent its locking end in a bore formed in the supporting bushing 108 for the indexer bar 90 and which bushing is secured in place by one or more lock screws 109. The plunger 107 at its opposite end has an enlarged diameter portion 110 that is slidable in a bore formed in an internal portion of the housing of the indexer I. A coil spring 111 surrounds the plunger 107 and at one end abuts the bushing 108 and at its opposite end the enlarged diameter portion 110 and functions to normally press or retract the plunger 107 in an unlocking direction. The outer end of the enlarged portion 110 is operatively connected to the arm 112 of an actuating bell crank lever that is fulcrumed to rock on a pin 113 carried in a suitable boss formed in the wall of the housing of the indexer I.

The short arm 114 of the bell crank lever can be designated as a cam follower arm and it is provided at its free end with a cam follower roller 115 normally held in engagement with the circumference of an actuating cam 116 due to the action of the spring 111. The cam 116 is secured to the rotating indexing cam 72 and is provided with a cam contour such that during the longitudinal right or left-hand indexing movements of the indexer bar 90 the lock plunger 107 will be held retracted against the action of the spring 111 while during the remaining or non-indexing rotation of the indexing cam 72 said locking plunger will be moved by the rocking of the bell crank against the load of spring 111 and locked or interengaged with one of the locking grooves 106, 106a, 106b or 106c so that the indexer bar 90 cannot be moved at this time from its indexed position.

It will be understood that as the cam 116 rotates with the indexing cam 72 when the cam follower roller 115 is

in engagement with the cam circumference portion indicated at 116a, which is a recessed portion, then the spring 111 will move the plunger 107 to retracted or unlocked position and the bell crank lever 112, 114 will be rocked in a counterclockwise direction as viewed in Fig. 10. Of course as soon as the cam follower roller 115 reengages the remaining circumference of the cam 116 said bell crank lever 112, 114 will be rocked in a clockwise direction and the locking plunger 107 will be moved and held in locking position against the action of the spring 111.

Referring to Figs. 2, 3, 6 and 7, the arms 100 of the sleeves 99 are pivotally connected to actuating rods 117, 118, 119 and 120, and which rods function respectively to effect selective inward movement of the cam follower pins 91, 92, 93 and 94 through the pins 102 and plungers 96.

Pattern or selecting mechanism

The actuating rods 117, 118, 119 and 120 are pivotally connected to the lower ends of the downwardly extending arms 121 of four bell crank levers which are rockable on a fixed shaft 122 carried by the frame 123 of the selector or pattern mechanism P of the weaving machine.

The four bell crank levers just referred to are located in juxtaposition to each other and have their other arms 124 extending substantially horizontally and with their free ends overlying a pattern chain indicated at 125 so as to be engaged by selectively positioned rolls 126 included in the chain. The pattern chain is well known in the art and a recognized example thereof is the commercially obtainable Crompton and Knowles Selector or Pattern Chain. It is not believed necessary in view of this to describe the pattern chain in detail. It will be understood that said chain may be provided with selecting rollers 126 arranged in any desired predetermined order so as to selectively engage the undersides of the arms 124 of the four bell crank levers to raise said arms upwardly and rock the vertical arms 121 of said levers in a clockwise direction to selectively exert a pulling force on the actuating rods 117, 118, 119 and 120 to project selectively one or another of the cam follower pins 91, 92, 93 and 94 to provide desired indexing movements for the indexer bar 90.

It will be understood that when a selecting roller 126 engages one of the arms 124 of one of the bell crank levers as the pattern chain moves around in its operative path during the operation of the weaving machine such roller will maintain the bell crank lever rocked a predetermined time period so as to maintain the particular cam follower pin of the indexer inserted in its cooperating cam groove in the indexing cam 72 until the drum has rotated sufficiently for said pin to leave the funnel-like portion of the groove, whereupon the roller 126 passes out of contact with the arm 124 of the bell crank lever after the indexing operation is completed and the cam follower pin and the parts operatively connecting said pin to the bell crank lever together with the latter are restored to normal position under the action of the spring 95.

The selecting rollers 126 will be arranged on the pattern chain 125 in predetermined order to produce the desired design in the fabric to be woven by the weaving machine. If the design to be woven in the fabric is a repetitive one the pattern chain 125 may be provided with repetitive series of prearranged rollers 126 located around the length of the endless pattern chain.

As will be understood in the art and in order to keep the length of the pattern chain to a minimum the pattern chain may be provided with multiplying rollers which cooperate with suitable mechanism known in the art for causing a single series of prearranged rollers 126 to function repetitively. Also the pattern chain 125 may be provided with reverse rollers that will operate through suitable mechanism to cause the rollers 126 to

function in reverse order at predetermined times during the operation of the weaving machine as will be well understood in the art.

If desired, the selector mechanism may be provided with a separate multiplier chain 127 and a separate reverse chain 128 that function through suitable mechanism to accomplish the purposes just above referred to and well understood in the art. However, for simplicity and to avoid complicating the present disclosure the weaving machine is illustrated and described as utilizing a pattern chain which may have only the rollers 126 mounted thereon to selectively actuate the bell crank levers and selectively effect the desired indexing movements of the indexer bar 90.

The pattern or selector chain 125 passes around sprockets 129 fixed to a shaft 130 rotatably supported in the frame of the selector mechanism (see Figs. 2 and 3) as will be well understood in the art. It will also be understood that said chains pass around idler sprockets not shown. The drive for rotating the shaft 130 to effect operative movement of the pattern chain 125 will now be described.

The shaft 67, Figs. 4 and 5, drives the driving member of a clutch, later to be referred to, the driven member of which is freely rotatable on the shaft 67 and carries a sprocket 131. A chain 134 passes around the sprocket 131 and around a sprocket 132 fixed on a harness drive shaft 133, see Fig. 3, and later to be referred to. The shaft 133 has fixed to it a second sprocket 135, see Figs. 3 and 4, which drives through a chain 136 a sprocket 137 fixed to a shaft 138, see Figs. 2 and 4. The shaft 138 is rotatably supported in suitable bearings in the frame of the selector or pattern mechanism P and has fixed thereto a miter gear 139 which constantly meshes with a miter gear 140 fixed on a shaft 141 that is rotatably supported in the frame, see Figs. 2 and 3.

The shaft 141 constitutes the drive shaft for the selector or pattern mechanism and is operatively connected through a gear train indicated generally at 142 in Figs. 2 and 3, to the driven shaft 130 of the mechanism. It will be seen that the selector or pattern mechanism containing the pattern chain is driven in the forward direction from the main drive shaft 58 through the shaft 67 and the driven member of the clutch thereon to the shaft 133 by the sprockets 131, 132 and chain 134 and thence from the shaft 133 to the shaft 138 by sprockets 135, 137 and chain 136, with shaft 138 being connected by the miter gears to the shaft 141 and the latter by the gear train 142 to the shaft 130.

Feeder box mechanism

The feeder box and feeder mechanism is indicated in its entirety at F in Fig. 2. Referring particularly to Figs. 7, 13 and 42 the feeder box 143 is of generally rectangular shape and on its side adjacent to the indexer I there is secured an elongated plate 144 provided with a connecting stud 145 that extends into the end of the indexer bar 90 and is secured therein wherefore the feeder box 143 will have transverse indexing movement imparted to it from the indexing movement of the bar 90. The feeder box 143 will index horizontally and in a direction transverse to the length of the box and substantially perpendicular to the direction of movement of the weft or filling threads. The feeder box 143 on its top and near the end of the box that is adjacent to the tensioner and brake mechanisms T and B is provided with a transversely extending guide support 146 having spaced guides for the four weft or filling threads X, Y, Z and W later to be referred to.

The feeder box 143 slidably mounts therein four weft or filling thread feeding and gripping assemblies indicated at 147 in Figs. 13, 14, 15 and 16. The assemblies 147 are arranged side by side for individual selection one at a time for sliding movement longitudinally

of the feeder box in a manner later explained and said assemblies move as a unit transversely with the feeder box during the indexing movements of the latter.

The filling or weft thread feeding and gripping assemblies 147 are each provided at their outer or right-hand ends as viewed in Figs. 13 and 16 inclusive with an upwardly extending actuating portion or plate 148 that is provided at its upper edge with a downwardly extending recess 149, the purpose of which will soon be apparent.

Each assembly 147 at its outer or right-hand end as viewed in the drawings is provided with a pair of spring arms 150 and 151 secured at their inner ends to the assembly 147 and provided at their outer ends with upwardly extending portions that constitute thread gripping spring jaws 152 and 153 and which grip a weft or filling thread but which can be opened to release said thread when it is transferred to the gripping jaws of a shuttle as will later be referred to.

The spring arms 150 and 151 adjacent their outer ends and below the level at which the jaws 152 and 153 grip the filling threads have their adjacent edges spaced apart as indicated at 154 and this space receives opening wedges later to be referred to that function to open the jaws 152 and 153 when the latter are in "transfer" position, at which time the filling thread is transferred to the shuttle and when in "pick-up" position wherein the jaws again grip the filling thread after the shuttle has been fired through the shed.

The assemblies 147 inwardly of the spring arms 150 and 151 are provided with an opening 155, see Fig. 16, to accommodate one of the two opening wedges when a particular assembly 147 is in "pick-up" position, at which time the other opening wedge is in the space 154 and functions to open the jaws 152, 153.

Lock bars 156 are secured to fixed portions of the machine so as to extend horizontally over the right-hand ends of the assemblies 147. The lock bars 156 have their adjacent or inner ends spaced apart to provide a slot 157 that is aligned with the path of movement of the shuttles through the shed. The lock bars 156 extend into the recesses 149 in the portions 148 of the assemblies 147, except as to the assembly 147 which underlies the slot 157 in any indexed position of the feeder box 143.

Referring particularly to Fig. 13 it will be observed that the feeder box 143 is in its most left-hand indexed position which corresponds to indexed position No. 1 of the indexer bar 90. At this time the left-hand lock bar 156 is located in the recesses 149 of the three left-hand feed and gripper assemblies 147 while the most right-hand assembly 147 underlies the slot 157. It will thus be seen that the three left-hand feeding and gripping assemblies 147 as viewed in Fig. 17 are locked against horizontal sliding movement while the most right-hand assembly 147 is free for such movement to be imparted thereto by the feeding mechanism later to be described.

It will be understood that as the indexer bar 90 is successively indexed from left to right from position No. 1 to positions Nos. 2, 3 and 4 the feeder box 143 will be similarly indexed. When the feeder box 143 is in indexed position No. 2 then the right-hand lock bar 156 as viewed in Fig. 17 will be located in the recess 149 of the most right-hand assembly 147, while the second from the right of the assemblies 147 will be aligned with the slot 157 between the lock bars and will be free for horizontal sliding movement.

It is not believed necessary to point out in greater detail how the lock bars 156 in each indexed position of the feeder box function to lock three assemblies against horizontal sliding movement while the remaining assembly 147 is aligned with the slot 157 and is free to have horizontal feeding movement imparted thereto.

The actuating mechanism or drive for imparting horizontal movements to the filling or weft thread feeding and gripping assembly 147 which is currently aligned with the slot 157 between the ends of the lock bars 156

will now be explained. Referring to Fig. 5, it will be seen that the main shaft 58 drives an idler gear 158 and said idler gear, in turn, constantly meshes with and drives a gear 159 fixed on a shaft 160 that is rotatably supported in suitable bearings in a portion of the picker box 62. The shaft 160 (see Fig. 20) has fixed thereto a cam 161 engaged by a cam follower shoe carried by a cam follower arm 162 which is fixed to the lower end of a vertically extending stub shaft 163 rockably supported in suitable bearings.

A feeder lever 164 has one of its ends mounted on the shaft 163 for free turning movement relative to the shaft. Above the feeder lever 164 and bearing on the latter is a short arm 165 which is clamped to the upper end of the shaft or pin 163 to rock with the latter. The short arm 165 adjacent its free end slidably mounts a plunger or detent 166 which is under a predetermined spring load exerted thereon by a spring 167 mounted in the arm 165 and acting on the inner end of the plunger or detent. The outer end of the plunger or detent 166 is beveled as indicated at 166a and said outer end cooperates with a keeper 168 secured to the upper side of the feed lever arm 164. The short arm 165 is provided in its upper wall with an opening 169 through which extends a pin 170, the opening 169 being of such size that the plunger or detent 166 can move to fully projected position under the load of the spring 167 or can be retracted against said load to disengage the end 166a from the keeper 168.

It will be seen that rotation of the shaft 160 and cam 161 acts through the cam follower arm 162 to rock in opposite directions the pin or stub shaft 163 and in turn to oscillate the short arm 165 and the feed lever arm 164 since the short arm is connected through the detent or plunger 166 and the keeper 168 to the feed lever arm 164 with a preloaded spring connection.

The arrangement just referred to is for purposes of safety in case movement of the feed lever arm 164 is prevented for some reason. Then the beveled end 166a of the plunger or detent 166 will ride out of the keeper 168 and said detent would be depressed against the load of the spring 167, thus disconnecting the drive from the arm 165 to the lever 164 and preventing damage to the parts.

The feed lever arm 164 has its outer end located above the slot 157 between the adjacent ends of the lock bars 156 and is operatively connected to a drive member 171 having on its lower edge a drive lug 172 which extends into the recess 149 of the portion 148 of the filling or weft thread feeding and gripper assembly 147 that currently underlies the slot 157 between the lock bars 156 and is free to have horizontal sliding movement imparted to it.

It will be understood that during the operation of the machine the feed lever arm 164 will be oscillated in predetermined timed relationship to the other operative parts of the weaving machine so as to engage in the recess 149 of the assembly 147 that is indexed to operative position beneath the slot 157 and to move said indexed assembly horizontally from "index" position as shown in Fig. 14 to "transfer" position as shown in Fig. 15 and then to "pick-up" position as shown in Fig. 16 and then back to "index" position to complete the cycle.

Referring to Fig. 42 it will be seen that the feed lever arm 164 on one side thereof is provided with a boss 173 which engages an adjustable but stationary stop screw 174 when the feed lever arm 164 is in "index" position. Also it will be seen that the opposite side of the feed lever arm 164 is provided with a boss 175 which engages the end of an adjustable but stationary stop screw 176 when the feed lever arm is in "pick-up" position.

When the feed lever arm 164 and the feeding and gripper assembly 147 to which it is operatively connected by the lug 172 are in "transfer" position an additional stop is provided in the form of a rod or bar 177 which has horizontal timed reciprocating movement such that

when the feeder and gripper assembly 147 is in "transfer" position said bar or rod will be projected into the path of the forward end of the portion 148 of the assembly 147 and will be engaged thereby as indicated in Fig. 15 and thus will act until withdrawn as a positive stop to further movement in the outward direction of the assembly 147 and also to further movement in the one direction of the feed lever arm 164.

For operating the stop rod or bar 177 in the proper timed relationship to the other parts of the weaving machine it may have its inner or non-stopping end operatively connected through a link 178 (see Fig. 41) with the operative arrangement indicated schematically at 179 that functions as the shuttle lifter in the weaving machine, as for instance, the shuttle lifter arrangement disclosed in Pfarrwaller United States Patent 2,578,205 as will be understood by those skilled in the art.

The machine is provided with a pair of spaced opening wedges 180 and 181 which move in proper timed relationship to the operative parts of the machine to effect opening of the jaws 152 and 153 of the feeder and gripper assembly 147 that is currently being actuated so that said jaws will release the filling thread in the "transfer" position and will close on the filling thread in the "pick-up" position.

The opening wedges 180 and 181 may be formed on the ends of the arms of a U-shaped member, not shown, but clearly illustrated in Pfarrwaller United States Patent 2,578,205 and which moves in proper timed relation to the other parts of the machine. In the "pick-up" position the opening wedge 181 moves into the space 154 between the arms 150 and 151 of the assembly to open the jaws 152 and 153 thereof and then moves out of said space 154 to allow said jaws to grip the filling thread, see Fig. 16, which the shuttle has carried through the shed.

When the assembly 147 is in "pick-up" position the opening wedge 180 is accommodated in the opening 155 in the assembly 147 as said opening wedge at this time is inactive. When the feeder and gripper assembly 147 is in the "transfer" position the opening wedge 180 moves into the space 154 to open the jaws 152 and 153 when the gripping jaws of the shuttle 182 have gripped the filling thread, after which the wedge 180 leaves the space 154 and said jaws 152 and 153 close and the filling thread has been transferred to the grippers of the shuttle, see Fig. 15.

Before describing the drag and brake mechanism B, the tensioner mechanism T and the detector mechanism D, and the drives to said mechanism, a résumé will be given of the functions and mode of operation of the indexer, feeder and pattern mechanisms during the operation of the weaving machine.

Assuming that the selecting rollers 126 have been properly located on the pattern chain 125 and the weaving machine is operating it will be understood that the rollers 126 will function in predetermined order to selectively rock in predetermined order the bell crank levers 121, 124 to effect predetermined indexing of the indexer bar 90 and of the feeder box 143 when the assemblies 147 therein are in "index" position as shown in Fig. 14 (Sheet 7). At this time one of the feeding and gripper assemblies 147 will underlie the slot 157 between the lock bars 156 and will be in a position to feed the filling or weft thread gripped by its jaws 152, 153 when moved to "transfer" position to the jaws of the shuttle 182 that is to be fired through the shed.

It will be recalled that the other three feeding and gripper assemblies 147 are locked at this time against horizontal sliding movement. However, the selective and successive positioning of the assemblies 147 in feeding position during the operation of the machine will result in the weft or filling threads X, Y, Z and W being successively transferred to the gripping jaws 183 of the shuttles 182 in a predetermined order to produce a de-

sired arrangement of filling threads of different color or types in the woven fabric.

Now reverting to Fig. 14, wherein the feeder and gripper assembly grasps the weft thread W and is in "index" position, it will be understood that the continued operation of the weaving machine causes this assembly 147 to move horizontally of the feeder box 143 from the "index" position of Fig. 14 to the "transfer" position of Fig. 15 (Sheet 4) through the instrumentality of the feeding mechanism and the engagement of the drive lug 172 in the slot 149 of the assembly 147. When the assembly 147 reaches "transfer" position it is engaged by the stop rod 177 and the opening wedge 180 moves into the space 154 between the arms 150 and 151 to open the jaws 152, 153 of the assembly 147 while the grippers 183 of the shuttle 182 grip the thread W and the shuttle is fired through the shed to the receiving box 63. As the shuttle 182 is fired through the shed the wedge 180 is removed from the space 154 of the assembly 147 and the stop rod 177 is retracted and said feeder and gripper assembly moves horizontally in a direction following the shuttle from the "transfer" position of Fig. 15 to the "pick-up" position of Fig. 16 wherein the opening wedge 180 passes into the opening 155 in the assembly 147 while the opening wedge 181 passes into the space 154 to open the jaws 152, 153, after which said opening wedges are retracted and the jaws 152, 153 grip the thread W. Then the assembly 147 with the jaws 152, 153 thereof gripping the thread W moves rearwardly horizontally from "pick-up" position of Fig. 16 to the "index" position of Fig. 14. When the assembly 147 has returned to "index" position it is either indexed with the feeder box 143 to an inactive position and a different assembly 147 is indexed to active position or the former assembly 147 can repeat its operation if the same weft thread is to again be fired through the shed.

It will be understood that the indexing movements and the feeding movements of the assemblies 147 are carried out in timed relationship to the firing of the shuttles 182 through the shed by the picker mechanism 184 which may be of the character illustrated and described in the hereinbefore mentioned patents and also in timed relationship to the forming of the sheds, the beating up of the weft threads and the other operations usual in weaving machines of this type.

The weft or filling threads X, Y, Z and W pass through the guides 146, the tensioner mechanism T, the drag and brake mechanism B and to the stationary packages 64 mounted in a package supporting frame indicated generally at 185 and which may be of substantially conventional form and which is supported on the left-hand end of the weaving machine as will be understood in the art.

Drag and brake mechanism

The filling or weft threads X, Y, Z and W as is usual in this type of weaving machine pass through drag devices 186 and brakes 187. The drag devices and the brakes per se are of conventional construction and it is the manner in which the drag devices and brakes of the multiple arrangement are selectively actuated that is novel herein. A brief description of the drag devices and brakes per se is all that is necessary for the reason just stated.

The drag devices and brakes are each four in number and are mounted on a fixed part of the machine in multiples corresponding to the number of weft or filling threads (see Figs. 35 to 40 inclusive, Sheets 12 and 13). These devices each include a shoe 188 arranged to normally bear on a tensioned metal strip 189, one end of which is secured to the fixed support for the drag devices and the brakes and the other end of which is secured to a supporting member 190 that is rockable on the spherical end of a rod 191 fixedly supported in the stationary supporting bracket forming part of the weaving machine.

The supporting member 190 has an angularly disposed portion at its lower end through which extends a vertical pin 192 that has its upper end fixed in the rod 191 and which adjustably mounts beneath the angularly disposed portion of the supporting member 190 a spring 193 and nuts 194 for varying the tension of the spring and for effecting tensioned rocking movement of the supporting member 190 about the spherical end of the rod 191 to tension the metal strip 189.

It will be understood that the drag device 186 and the brakes 187 are provided in multiples of four corresponding to the number of weft threads and that each of said devices and brakes are similarly constructed.

Each of the shoes 188 of the drag devices is connected to one end of an actuating arm 195 of a multiple series of arms which is pivoted on a shaft 196 located adjacent the other end of the arm, there being four of the actuating arms 195, all of which are pivotally mounted on the shaft 196 and normally are in a position wherein the shoes 188 engage the metal strips 189. Similarly the shoes 188 of the brakes are connected to one end of actuating arms 197 which are also pivoted on the shaft 196. The arrangement whereby the arms 195 and 197 are selectively raised in correlation to the indexing of the feeder box 143 and to the particular weft thread that is currently being fired through the shed will now be explained.

The feeder box 143 at its left-hand end as viewed in Fig. 13 has fixed thereto as a part thereof the tensioner block later to be referred to and including an end plate or drag and brake block indicated at 198, see also Fig. 35. A lever arm 199 is pivoted intermediate its ends as indicated at 200 to a stationary part of the machine and one end of said lever arm is pivotally connected to the drag and brake block 198.

It will be apparent that indexing movement of the feeder box 143 to any of positions Nos. 1, 2, 3 and 4 for the feeding selectively of the weft or filling threads X, Y, Z and W will impart a correlated rocking movement to the lever arm 199 about its pivot 200.

The other end of the lever arm 199 is pivotally connected to one end of a link 201, the opposite end of which is pivotally connected to a projecting arm 202 formed on the hub 203 which is rockable on a post 204 and also 45 is slidably vertically on said post.

The hub 203 is provided with a brake actuating portion 205 which carries four predeterminedly spaced adjustable lifting screws 206, the purpose of which will later become evident. The hub 203 also has a projecting arm 50 207 which is pivotally connected to one end of a link 208, the opposite end of which link is pivotally connected to a projecting arm 222 on a hub 209 similar to the hub 203 and provided with a drag actuating portion 210.

The hub 209 is rockable and axially movable on a 55 fixed post 211 while the drag actuating portion 210 is provided with four lifting screws 206 as was the portion 205 of the hub 203. It will be understood that as the feeder box 143 indexes the indexing movement will be imparted through the lever arm 199, link 201 to the hub 60 203 and through the link 208 to the hub 209, wherefore the brake actuating portion 205 and the drag actuating portion 210 will have equalized and similar movements such that a particular lifting screw 206 of each actuating portion will be positioned under a particular actuating arm 197 and actuating arm 195 in correlation to the filling thread that is to be fed to the shuttle in the particular indexed position of the feeder box, that is, one of the lifting screws 206 of the brake actuating portion 205 and of the drag actuating portion 210 will be aligned with an 65 abutment member 212 of a particular actuating arm 195 and actuating arm 197 so that axial movement of the hubs 203 and 209 will cause engagement of the specified screw 206 of each of the portions 205 and 210 with its cooperating abutment member of the lever arms 195 and

The upper cam shaft 160 has fixed thereto a drag actuating cam 213 (see Fig. 29 Sheet 10) and a brake actuating cam 214. The drag actuating cam 213 has its periphery engaging a plunger 215 while the brake actuating cam 214 engages a plunger 216. The plungers 215 and 216 are arranged in different planes and the outer ends of said plungers engage one arm, respectively, of similar rockable bell crank levers mounted coaxially one above the other, one of which is shown at 217 in Fig. 29. The other arms of the two bell crank levers actuate, respectively, push rods 218 and 219. The push rod 218 is operatively connected to a rockable lifter member 220 suitably supported in the machine and having a lifter portion 221 underlying the arm 222 formed on the hub 209. It will be seen that the drag cam 213 will actuate the plunger 215 during a predetermined time period in the operation of the weaving machine to rock its cooperating bell crank lever 217 and depress the push rod 218 to rock the lifter member 220, whereupon the lifter portion 221 thereof will act on the underside of the arm 222 of the hub 209 to raise said hub and the drag actuating portion 210 thereof to cause the lifting screw 206 of said portion that is aligned with its cooperating abutment member 212 to engage the latter and raise the arm 195 which carries it to release the drag shoe 188 on the outer end of the arm.

The push rod 219 is operatively connected to a lifter member 223 similar to the lifter member 220 and which has a lifter portion 224 that cooperates with an arm 225 formed on the hub 203, see Figs. 35, 37 and 38. It will be understood that when the brake cam 214 actuates the plunger 216 the latter's cooperating bell crank lever 217 will be rocked to move the rod 219 and rock the lifter member 223 so that the lifter portion 224 thereof engages the underside of the arm 225 and raises the hub 203 to effect raising of one of the brake arms 197 and the release of the brake associated therewith.

It will be understood that one drag and one brake of the multiple series of drags and brakes will function during each indexed position of the feeder box 143 and upon the currently selected weft or filling thread that is being thrown through the shed. It will also be understood that this one drag and one brake will be released and applied during predetermined portions of the picking operation as is usual in weaving machines of this type.

Generally speaking, the brake will be applied prior to the indexing of the feeder box and during the firing of the shuttle through the shed and just prior to the shuttle reaching the receiving box and will be off or released during the remainder of each picking operation. Also the drag will be on or applied during the major portion of the firing of the shuttle through the shed and at all other times except when the filling thread feeding and gripper assembly 147 is moving from "index" position to "transfer" position wherein the thread is transferred from the assembly to the shuttle.

It will be understood that the primary purpose of the brake is to retard the movement of the filling thread currently being fired through the shed just before the shuttle reaches the receiving box in order to prevent excess thread from being withdrawn from the package. The purpose of the drag is to maintain substantially at all times, except during the feeding of the thread to the shuttle, a predetermined drag or load on the thread to maintain a tension thereon.

Tensioning mechanism

Referring to Figs. 28, 29 and 30, Sheet 10, it will be seen that the upper cam shaft 160 is operatively connected at its end to an extension sleeve 226 fixed to a spacer sleeve 227 in turn fixed to the shaft 160 and located between the brake cam 214 and a nut threaded on the end of the shaft 160.

The extension sleeve 226 is fixedly connected to a hub 228 mounted to rotate on suitable antifriction bearings 229 carried by a fixed stub shaft 230 arranged in

axial alignment with the shaft 160. Secured to the hub 228 between the end of the extension sleeve 226 and a clamping plate 231 by the securing bolts 232 are axially spaced cams 233 and 234.

The housing for the stub shaft 230 below the level of the said stub shaft and parallel thereto rockably mounts a tensioning arm actuating shaft 235. The shaft 235 is provided with axially spaced roller carrying flanges or members 236, 236a and 237. The flanges 236, 236a and 237 in this instance are integral with the shaft 235 and include radially extending end flanges 236 and 237 and an intermediate radially extending flange 236a. The flanges 236 and 236a mount therebetween a cam follower roller 238 while the flanges 236a and 237 mount therebetween a cam follower roller 239. The cam follower rollers 238 and 239 are located on substantially diametrically opposite sides of the shaft 235 and the roller 238 cooperates with the cam 233 while the roller 239 cooperates with the cam 234.

It will be seen that rotation of the upper cam shaft 160 rotates the extension sleeve 226, hub 228 and cams 233 and 234 and the latter acting on the rollers 238 and 239 impart rocking movement to the shaft 235. The shaft 239 extends outwardly of the housing and a tensioning arm 240 is mounted coaxially on the outwardly extending end thereof to have rocking movement relative to said shaft and also with said shaft as will later be pointed out (see Figs. 23 and 30).

The short arm or lever 241 similar to the previously described short arm 165 is fixed to the outer end of the shaft 235 to rock therewith. The short arm or lever 241 overlies the tensioning arm or lever 240 and mounts a spring loaded plunger, the outer or beveled end 242 of which normally engages in a keeper 243 secured to the outer side of the arm or lever 240, see Fig. 3. The arrangement just described constitutes in effect a safety clutch arrangement such that should movement of the arm or lever 240 be prevented the operative connection between it and the short arm 241 will be released and the latter can continue to rock, thus avoiding breakage of parts.

The arrangement just described is similar to the arrangement for oscillating the feed lever arm 164 previously described. The purpose of the tensioning arm or lever 240 will shortly become apparent.

The feeder box 143 has secured to it for indexing movement therewith in a direction transverse to the direction of movement of the filling threads a tensioning rod supporting block 244, see Figs. 13 and 22 Sheets 7 and 9. The block 244 is provided with a series of four guideways for tensioning rods 245, said guideways being spaced apart in the transverse direction of the feeder box 143 and each including vertically spaced rod guiding portions 246, 247 and 248, see Fig. 24, Sheet 10.

The rods 245, which will later be referred to, have secured to their lower ends beneath the guiding portions 248 actuating shoes 249 provided on one side with a rectangular recess 250, see Fig. 27, and the purpose of which will later become apparent. It will be understood that as the feeder box 143 is indexed in its transverse direction the block 244 and the four series of vertically disposed guide portions for the rods 245 will be correspondingly indexed.

A stationary support indicated in its entirety at 251 is arranged in the machine below the plane on which the feeder box 143 and block 244 index and said support 251 includes a vertically extending member 252, the upper end of which forms a supporting surface 253 for the lower ends of the actuating shoes 249 of three of the tensioning rods 245 in each indexed position of the block 244 and feeder box 143.

The member 252 is provided with a slot 252a with which the actuating shoe 249 of the fourth tensioning rod 245 aligns and in which the shoe 249 of said rod can slide vertically downwardly, it being understood that this

fourth tensioning rod is the one that functions with the weft or filling thread that is currently being operated on in the indexed position of the feeder box 143.

The stationary support 251 also includes a vertically disposed stationary guide plate 254 provided with a vertical slot 255 which is parallel to and communicates with the vertical slot in the member 252 of the support and in which latter slot the shoe 249 on the index rod 245 can move vertically. The free end of the tensioning arm or lever 240 extends over the guide plate 254 and is pivotally connected to one end of a link 256, the opposite end of which link is pivotally connected to a slide 257.

The link 256 and slide 257 extend beneath the guide plate 258 forming part of the support 251 and spaced from the vertical guide plate 254 and which functions to maintain the slide 257 against the plate 254 and with the pin 259 of the slide extending through the vertical slot 255 in the plate 254 so that its inner end can be engaged in the recess 250 of the shoe 249 of the tensioning rod 245 that is in indexed position and which overlies the vertical slot in the member 252 and supporting surface 253.

The indexing of the feeder box 143 occurs when all four of the rods are in raised or tensioning position as indicated in full lines in Fig. 23. At this time and throughout the indexing of the feeder box 143 and the tensioning rod supporting block 244 the end of the tensioning arm or lever 240 is maintained in engagement with the adjustable stop 260 carried by the support 251.

It will be understood that when the parts are in the position just referred to, such as shown in Fig. 23 and the feeder box 143 and block 244 are indexed, then the projection 259 of the slide 257 leaves the recess 250 of the shoe 249 of the tensioning rod 245 that previously was in active position and enters into the recess 250 of the shoe 249 of the tensioning rod that is indexed to active position. Then prior to the shuttle being fired through the shed to carry across the weft thread that is associated with the now active rod 245, the shaft 235 is rocked by its drive previously described to cause the tensioning arm or lever 240 to move downwardly from the full line position of Fig. 23 to the dash line position thereof and such movement is transmitted through the link 256 to the slide 257 and to the projection 259 and the shoe 249 of the currently active tensioning rod to move the latter downwardly to the dash line position of Fig. 23 and provide the necessary slack in the weft thread for the picking operation with respect to said thread.

After the shuttle with the currently active weft thread connected thereto reaches the receiving box on the other end of the weaving machine the arm 240 is actuated from its broken line position in Fig. 23 to its full line raised position to tension said weft thread and subsequently in the event that the block 244 is indexed with the feeder box 143 to connect the projection 259 with the shoe 249 of another tensioning rod 245 that is to be the active rod during this following picking operation.

The tensioning rods 245 have fixedly secured in their ends opposite to the ends mounting the shoes 249 tensioning pins or needles 261 carrying guiding bushings 262 provided with filling thread guiding eyes 263 through which the filling threads pass, see Fig. 27.

In Figs. 31 through 34 inclusive there is shown a modified form of filling thread tensioning mechanism from that previously described. In this modified form the supporting and guiding structure for the tensioning rods 245 is stationary and does not index with the feeder box 143 as was the case in the previously described form.

Referring to Figs. 31 to 34 inclusive the support includes a back plate 264 that is secured in vertical position to a fixed part of the weaving machine and is provided with four spaced vertically extending guideways 265 in which the actuating shoes 249 of the tensioning rods 245 have sliding movement.

At the upper end of the back plate 264 is a guiding

and spacing block 266 secured to the back plate 264 and to a front plate 267 and acting to space the front plate from the back plate. The block 266 is provided with four transversely spaced vertically extending guide openings through which the tensioning rods 245 extend. An indexible tensioning rod supporting device extends transversely between the back plate 264 and front plate 267 and this device comprises a guiding and supporting rod 268 which has sliding and supporting movement in an opening formed through the back plate 264 in the transverse direction.

The rod 268 adjacent its opposite ends extends through and is secured to the arms 269 and 270 of a substantially U-shaped member, the base 271 of which extends horizontally substantially midway between the back plate 264 and the front plate 267. The base 271 is formed of two separate aligned parts providing between their adjacent inner ends a gap 272. The base 271 extends through the recesses 250 of three of the shoes 249 on the tensioning rods 245 while the gap 272 is aligned with the recess 250 in the shoe 249 of the fourth tensioning rod 245, and which of the tensioning rods constitutes the fourth rod depends upon the indexed position of the base 271.

In order to index the base 271 in conformance with the indexing movement of the feeder box 143 the latter has secured to it for indexing movement therewith a bar 273. The bar 273 at its free end pivotally mounts a shoe 274 which is located between the tines of the bifurcated end 275 of an actuating lever 276 that is pivoted midway of its ends to a stationary part of the machine as indicated at 277. The bifurcated end 278 of the lever 276 slidably receives a shoe 279 that is pivotally connected to the upper end of the arm 269 of the U-shaped indexible member.

It will be seen that indexing movement of the feeder box 143 will impart a similar indexing movement to the base 271 but in the opposite direction through the bar 273 and the lever 276. The free end of the tensioning arm or lever 240 is pivotally connected to one end of a link 280 the opposite end of which link is pivotally connected to a vertically sliding plate 281. The plate 281 is provided with a transversely extending elongated slot 282 which in the uppermost position of the plate aligns with the base 271 of the substantially U-shaped indexible member and the recesses 250 in the shoes 249 of the tensioning rods 245.

An actuating shoe 283 is slidable on the plate 281 and has a portion 284 that is guided in the slot 282 of the plate. The actuating shoe 283 is held in assembled relationship with the guiding portion 284 thereof in the slot 282 by the front plate 267, see Figs. 32 and 33. The portion 284 of the actuating shoe 283 has a post 285 that is substantially rectangular in shape and extends through the gap 272 in the base 271 of the substantially U-shaped indexible member and into the recess 250 of the actuating shoe 249 of the tensioning rod 245 that is aligned with said slot.

It will be seen that when the feeder box 143 is indexed the base 271 will be indexed in correlation therewith although in the opposite direction and this indexing movement of the base 271 will cause the post 285 to move from the recess 250 of the shoe 249 in which it was engaged into the recess 250 of another and predetermined shoe 249 of one of the tensioning rods 245. This movement of the post causes sliding movement of the portion 284 in the slot 282 and sliding movement of the actuating shoe 283.

During the indexing of the feeder box and of the substantially U-shaped indexible member, as just referred to, the tensioning arm or lever 240 is in its uppermost position as indicated in full lines in Fig. 31. When the indexing has been completed and the feeding and picking of the filling is occurring the tensioning arm or lever 240 is moved from its full line position of Fig. 31 to its broken line position and this causes downward sliding movement

of the plate 281, shoe 283 and post 285 to bring about downward sliding movement of that tensioning rod 245 whose actuating shoe 249 has the post 285 engaged in its recess 250 and this downward movement of the tensioning rod 245 provides slack in the weft or filling thread that is currently being fired through the shed with the shuttle to which it has been transferred.

When the shuttle reaches the receiving box on the other end of the weaving machine the tensioning arm or lever 248 moves from its broken line position of Fig. 31 to its full line position to raise the previously lowered tensioning rod 245, after which all of the four tensioning rods 245 are in their raised positions until the indexing of the feeder box 143 has been completed and the feeding and firing through the shed of a newly selected filling thread is occurring.

Detector mechanism

The tensioning rods 245 are located intermediate the filling thread guide block 146 and the filling guides 286 which are adjacent to the drag and brake mechanisms. Intermediate the guide block 146 and the tensioning rods 245 a detector rod 287 extends beneath all four of the filling threads. The detector rod 287 is secured to the end of an extension shaft 288 that is operatively connected with a shaft 289 as indicated by the coupling element 290 in Fig. 13. The shafts 288 and 289 are rockably supported in spaced bearings provided in the machine and indicated at 291 and 292 in Fig. 13.

The shaft 289 extends into the picking box 62 and its motion is derived from mechanism contained in the picker box but not illustrated herein as per se it forms no part of the present invention and is well understood in the art.

It will be understood that the mechanism just referred to is operatively connected to the master stop rod 81a of the weaving machine and includes means for urging rocking movement of the shaft 289 under a spring load in a direction to rock the shaft 288 and raise the detector rod 287 and such raising movement of the detector rod 287 functions to actuate the master stop rod 81a to disengage the main clutch and apply the brake in the housing 61 so as to stop rotation of the main drive shaft 58 of the weaving machine.

The filling detector 287 functions similarly to the standard picking side detector in weaving machines of this type. As previously stated, the detector rod 287 extends beneath all four of the filling threads X, Y, Z and W. During the insertion of a particular filling thread in the shed its tensioning rod 245 is lowered so that said particular filling thread engages the detector rod and the latter is prevented thereby from swinging upwardly under the spring load that tends to rock the shafts 289 and 288. At this time the unselected filling threads carried by the other three tensioning rods 245 are held in elevated position and out of contact with the detector rod. Consequently should the selected filling thread break or become unduly slack through some operative fault the detector rod then will be free to swing upwardly and as previously stated such movement of the detector rod will effect actuation of the master stop rod 81a and immediately stop the operation of the weaving machine. It will be understood that during those portions of the cycle of operation in which all four tensioning rods 245 are in raised position suitable mechanism operatively associated with the shaft 289 and the master stop rod 81a will lock said shaft 289 against rocking movement and the detector rod will remain in its lower position and the master stop rod 81a will not be actuated to stop the operation of the weaving machine.

Pick back safety device

The shaft 71 and indexing cam 72 rotate in a forward direction and are not reversible. However during a "pickback" operation to rectify a filling thread irregularity

in the fabric the drive to the selecting or pattern chain mechanism is reversible.

Assuming that thread or other failure causes actuation of the master stop rod 81a to stop the operation of the machine at a time when the indexing cam 72 is in the indexing portion of its rotation, it is clear that a "pick back" should not then be effected. The initiation of the "pickback" operation would cause the selector or pattern chains to be operated in the reverse direction for one complete "pick back" operation and this would result in the pattern chain acting to insert a different cam follower pin into the groove in the indexer cam 72 than the pin that is currently in its groove, and since this cannot occur the parts would be damaged.

It is important that means be provided for preventing the initiation of a "pick back" operation when the indexer cam 72 is in the indexing portion of its rotation so as to avoid all danger of jamming up the machine or causing the breakage of parts.

As previously stated, the sprocket 131 is carried by the driven member of a clutch 293 freely rotatable on the shaft 67 and coacting with the driving member of the clutch which is fixed to the shaft 67. The clutch 293 is a one revolution clutch which is fully shown and described in Moessinger Patent 2,639,732 covering a "pick back" mechanism for a weaving machine of the general type of the instant weaving machine and hence it is not necessary to set forth herein a detailed description of said clutch 293.

As previously described, the sprocket 131 drives through a chain 134 a sprocket 132 fixed on the shaft 133 which also has fixed thereto a second sprocket 135 which through the chain 136 drives the selecting or pattern chain mechanism. The shaft 133 carries a gear 294 which is in the "pick back" drive that includes a gear 295 meshing with the gear 294 and carried by a "pick back" drive shaft 296. The gear 294 is freely rotatable on the shaft 133 and is connected to the driving element 297 of a "pickback" clutch, the driven element 298 of which is splined to the shaft 133 for rotation therewith and movement axially thereof. Reference is made to said Moessinger Patent 2,639,732 for a fuller disclosure of the "pickback" drive and "pick back" clutch.

The clutch 293 on the shaft 67 is a spring loaded clutch and includes a pawl or pawls engageable in slots of the driving member of the clutch when the clutch is disengaged, that prevents the driving and driven members thereof from returning to normal operating engagement during one rotation in the reverse direction of the sprocket 131 and the driven member of the clutch to which the sprocket is fixed.

Referring to said Moessinger Patent 2,639,732, it will be understood that during a "pickback" operation the sprocket 131 and the driven member of the clutch will be driven from the shaft 133 in the reverse direction and at such time the shaft 67 is stationary.

Referring to Figs. 2 and 3, the "pick back" control lever is shown at 299 and said lever is connected to a vertically extending shaft 300 to effect manual rocking movement of said shaft 300 in one direction while rocking movement in the opposite direction is imparted thereto by spring means when the operator releases the lever 299, as clearly described in said Patent 2,639,732.

As in the construction shown in said Patent 2,639,732, the lower end of the "pick back" control lever shaft 300 is provided with an eccentric which actuates a rod 301 when the shaft 300 is rocked and said rod 301 is pivotally connected to a link 302 which at one end is pivotally connected to a rockable lever 303 and at its other end is pivotally connected to a rod 304 with said latter named rod being operatively connected to the shiftable driven element 298 of the "pick back" clutch.

When the shaft 300 is rocked against its spring load by manually pulling the control lever 299 the eccentric at the lower end of the shaft 300 pulls the rod 301 which

in turn actuates the link 302 and the lever 303 to cause the spring loaded clutch 293 to disengage, whereupon the pawl associated with the clutch 293 prevents it from returning to engaged position for one revolution in the reverse direction. The movement of the lever 303 moves a trip rod 305 which rocks a trip lever 306 to cause shifting of the rod 307 to actuate the master stop rod 81a to which the rod 307 is operatively connected.

The actuation of the master stop rod 81a disengages the main clutch of the machine and applies the brake and terminates rotation of the main drive shaft 58 and the drive to the indexing cam 72 and the forward drive to the selecting or pattern chain mechanism stops. However, at this time the "pick back" drive to gear 294 continues but said gear is not operatively connected to the shaft 133 but is freely rotatable thereon.

When the operator releases the control lever 299 the spring load on the shaft 300 rocks said shaft in the reverse direction and the eccentric at the lower end of the shaft acts upon the rod 301 and through link 302 upon the rod 304 to effect engagement of the driven member 298 with the driving member 297 of the "pick back" clutch, whereupon the shaft 133 is driven in the reverse direction through the gear 294. The reverse drive of the shaft 133 drives the sprocket 135 on the shaft 133 in the reverse direction and from said sprocket the selecting or pattern chain mechanism in the reverse direction. Also the sprocket 132 on the shaft 133 is driven in the reverse direction and this causes reverse rotation of the sprocket 131 that is fixed to the driven member of the clutch 293. However, as soon as the driven member of the clutch 293 has made one revolution in the reverse direction it is engaged with its driving member under the spring load of the clutch, the pawl previously referred to moving to a position where this engagement is permitted. When the clutch 293 returns to normal engaged position the spring of said clutch actuates lever 303 and link 302 to disengage the elements 297 and 298 of the "pick back" clutch and to cause the trip rod 305 to return to its normal position. Thus one "pick back" operation in the reverse direction is effected.

When the operator desires to start the normal operation of the machine he manually effects reengagement of the main drive clutch and release of the brake that are contained in the housing 61. Reference may be had to said Moessinger Patent 2,639,732 for a fuller explanation of the functioning of the parts for the "pick back" operation. In order that the "pick back" operation cannot be started when the indexing cam 72 is in that portion of a rotation which is the indexing portion the following arrangement is provided.

The eccentric on the lower end of the shaft 300 previously referred to includes a block 308 which normally has rocking movement in a horizontal plane. The block 308 rockably mounts a pin 309 which has fixed to it a stop arm 310 and said arm 310 which rocks relative to block 308 is normally held by a spring 311 against a shoulder 312 on the block 308 when said block moves with the shaft 300 under the manual actuation of the "pick back" control lever 299. However, when said shaft 300 and the block 308 are rocked under the spring load when the control lever is released said stop arm 310 and pin 309 can rock relative to the block 308 against the action of the spring 311 with said stop arm moving away from the shoulder 312. The stop arm 310 is provided with a locking notch 313 adapted to receive the locking portion 314 projecting radially from a lock collar 315 fixed to the shaft 133. When the locking portion 314 of the collar 315 is located in the notch 313 the block 308 and shaft 300 cannot be rocked manually by the operator swinging the "pick back" control lever 299. The locking portion 314 of the lock collar 315 is so positioned and is of an arcuate length such that during the indexing portion of each rotation of the indexing cam 72 the locking portion 314 will be engaged in the locking

notch 313 and hence the operator cannot at such time initiate a "pick back" operation.

Operation of the machine

- 5 In order to coordinate the functions of the mechanisms and devices hereinbefore described and to show the advantages and utility present in a weaving machine embodying the same, the description of the operation of the machine will now be set forth. Insofar as the machine operates in the usual and well known manner reference to such phases of its operation need not be specifically referred to. It will be understood that the movement of the warp threads through the machine, the operation of the heddle frames to form the sheds, the actuation of the reed for the beat-up operation, the receiving of the shuttles in the receiving box, the cutting and tucking in of the weft threads, and the return of the shuttles to picking position are all carried out in the usual manner.
- 10 It may be assumed that the weft or filling threads W, Z, Y and X are, in this instance, of different colors. It may also be assumed that the weft or filling threads W, Z, Y & X are correlated to indexed positions Nos. 1, 2, 3 and 4, respectively, of the indexer bar 90 and the feeder box 143. It may further be assumed that the rollers 126 have been properly positioned on the pattern chain 125 so as to produce repetitive cycles of operation in each cycle of which weft or filling threads W, Z, Y and X are successively fired through the shed. Now assuming that
- 15 the machine is operating and one of said cycles is to be initiated, the proper roller 126 of the pattern chain will actuate the proper arm 124 of a bell crank lever to effect actuation of the rod 117 to cause insertion of the most left-hand cam follower pin 91 into the wide portion 84 of its coacting groove in the indexing cam 72. At this time the drag and brake mechanisms B are on and all four of the tensioner rods 245 are in raised or tensioning position while the feeding or gripper assembly 147 for filling thread X is in "index" position following its return from "pick up" position. The continued rotation of the indexing cam 72 causes the inner end of the cam follower pin 91 to engage the full length of the inclined wall portion 86 of its coacting groove in the indexing cam 72 and as the latter rotates the indexer bar 90 and the feeder box 143 are indexed three steps from their most right-hand or No. 4 position to their most left-hand or No. 1 position as viewed in Figs. 2 and 42.
- 20 When the indexing has been completed and gripper assemblies 147 for the filling threads X, Y and Z are held against horizontal movement by the lock bar 156 while the assembly 147 for the filling thread W is aligned with the slot 157 between the adjacent ends of the lock bars 156 and is free for horizontal longitudinal movement under the action of the lug 172 of the drive member 171. At this time the locking disk 194 has entered its cooperating locking groove 103 in the indexer bar 90 and said bar and the feeder box 143 are locked against indexing movement.
- 25 The feeding and gripper assembly 147 for the filling thread W is now moved horizontally from "index" position to "transfer" position where it is engaged by stop rod 177 while opening wedge 180 opens its gripping jaws 152, 153 to transfer filling thread W to the grippers of a shuttle 182. The shuttle 182 is then fired through the shed carrying filling W therethrough. As soon as the firing of the shuttle 182 commences the stop rod 177 is retracted and the feeding and gripper assembly 147 for filling W moves forwardly longitudinally from "transfer" position to "pick up" position wherein its jaws 152 and 153 again grip filling W.
- 30 During the movement of the assembly 147 from "index" position to "transfer" position the brake and drag mechanisms are off while the tensioning rod 245 for filling W moves downwardly from its raised position to its lower position wherein filling W rests upon detector rod 287

- 70
- 75

while the other three tensioning rods 245 remain in raised position.

During the firing of the shuttle 182 to carry filling W through the shed the brake and drag mechanisms are applied to prevent an undue amount of filling W being withdrawn from the package 64 and producing unwanted slack in the filling. It will be understood that should filling thread W break as it is being carried through the shed and prior to being gripped by the assembly 147 in the pick up position, then detector rod 287 would move upwardly to actuate the master stop rod 81a and stop the operation of the machine.

Now assuming the filling W is properly positioned in the shed and has been severed and tucked and beat up into the warp, it will be understood that during such time the assembly 147 returns from "pick up" position to "index" position with the jaws 152, 153 thereof gripping the filling W. During the return of the assembly 147 from "pick up" position to "index" position the tensioner rod 245 for filling W moves upwardly to its raised position to take up slack in the filling W. During the return of the assembly 147 to "index" position the cam follower pin 91 has been retracted under the action of its spring 95 and the cam follower pin 92 has been inserted in the wide portion 84 of its cooperating cam groove in the indexing cam 72. As the indexing cam 72 rotates the inner end of the pin 92 when the cam reaches the indexing portion of its rotation engages inclined wall 87 and this occasions a one-step indexing movement to the right, as viewed in the drawings, to be imparted to the indexer bar 90 and the feeder box 143, whereupon the feeding and gripper assemblies 147 for the filling threads X, Y and W are locked against longitudinal movement by the lock bars 156 while the assembly 147 for the filling Z is aligned with the slot 157 between the adjacent ends of the lock bars and is free to have longitudinal movement imparted thereto by the lug 172 of the drive member 171. Then the assembly 147 for the filling Z moves from "index" position to "transfer" position wherein the filling Z is transferred to the shuttle and then it follows the firing of the shuttle to the "pick up" position wherein its jaws 152, 153 again grip the filling Z.

It will be understood that the brake and drag mechanisms and the tensioner rod 245 for the filling Z function similarly to the mechanisms and the tensioner rod for the filling W as previously described during the movements of the assembly 147 and the firing of the shuttle. It will also be understood that during the firing of the shuttle with the filling Z the detector rod 287 is in engagement with the filling Z.

Now assuming that the assembly 147 for the filling Z has returned to "index" position and the cam follower pin 92 has been retracted by its spring 195 and the cam follower pin 93 inserted through the action of the pattern chain into its groove in the indexing cam 72, the inner end of said pin 93 during the last half of the indexing portion of the rotation of the indexing cam 72 engages the inclined wall 88 and the indexer bar 90 and feeder box 143 are indexed one step toward the right to index position No. 3. In index position No. 3 the feeding and gripper assemblies 147 for filling X, Z and W are held against longitudinal movement by the lock bars 156 while the assembly 147 for the filler Y is aligned with the slot 157 and is free to have longitudinal movement imparted thereto.

Now the assembly 147 for filling Y is moved from "index" position to "transfer" position wherein the filling Y is transferred to the shuttle 182, after which the shuttle is fired through the shed, the assembly 147 moves to "pick up" position and regrips filling Y and then returns to "index" position as previously described in connection with fillings W and Z. During this time cam follower pin 93 is retracted by its spring 95 and cam follower pin 94 is projected into the wide part of its groove in the indexing

cam 72. The inner end of the pin 94 contacts the inclined wall 89 during the last third of the indexing portion of the rotation of the indexing cam 72 to effect a one step right-hand indexing movement to the index bar 90 and feed box 143 to No. 4 indexed position. At this time the assemblies 147 for filling threads Y, Z and W are held against longitudinal movement by the lock bars 156 while the assembly 147 for the weft thread X is aligned with the slot 157 and is free to move longitudinally from "index" position to "transfer" position to "pick up" position and then back to "index" position. It will be understood that during the time this assembly 147 is moving from "transfer" position to "pick up" position the shuttle 182 with filling X connected thereto is fired through the shed.

When the assembly 147 for filling X has returned to "index" position the cam follower pin 94 will have been retracted by its spring 95 and the pattern chain will function to effect projection of the cam follower pin 91 into the wide portion of its cam groove in the indexing cam 72. Hence during the rotation of the indexing cam in the indexing portion thereof the inner end of pin 91 will engage inclined wall 86 and effect a three-step left-hand indexing movement of bar 90 and feed box 143 from index position No. 4 to index position No. 1 and this will cause the feeding and gripper assembly 147 for weft W to be aligned with the slot 157 while the assemblies 147 for fillings X, Y and Z are locked against longitudinal movement by the lock bar 156. The cycle of operation just above explained will now be automatically repeated by the machine for the illustrative cycle selected.

It will be understood that the filling threads X, Y, Z and W can be inserted into the fabric in any desired order other than the one selected for illustrative purposes. Also it will be understood that the four filling threads need not all be of different colors, and, in addition, that the machine can be set up to operate on the basis of utilizing a single filling thread, of alternating the use of two different filling threads or of using in predetermined order three different filling threads. Likewise, the pattern chain can be so prepared that the filling threads are selectively utilized in any desired order or arrangement and not necessarily in the same repetitive cycle explained.

It will be understood that should it be necessary to effect a "pick back" operation as for instance in the case of a filling thread being improperly inserted or becoming broken, the operator cannot actuate the "pick back" control lever 299 as long as the indexing cam 72 is in the indexing portion of its rotation, since the device illustrated, particularly in Figs. 44, 45 and 46 will prevent this. Consequently the danger is eliminated of attempting, during the indexing portion of the rotation of the indexing cam, to insert a cam follower pin into its cam groove in the indexing cam 72 while another cam follower pin is already inserted into its groove and thus possible damage to the parts is avoided.

The foregoing description indicates that a weaving machine of the gripper shuttle type embodying the described invention fully accomplishes the objects hereinbefore stated and has great versatility in its weaving operations and in the production of woven fabrics including various designs and filling thread arrangements.

Although specific structural forms embodying the invention have been specifically illustrated and described herein, it will be understood that the invention is susceptible of various modifications and adaptations within the scope of the appended claims.

Having thus described our invention we claim:

1. In a weaving machine of the gripper shuttle type, a weft or filling thread selecting mechanism comprising a feeder box containing in side by side relationship a plurality of feeding and gripping assemblies each correlated to a separate weft or filling thread and individually linearly movable longitudinally of said feeder box, means for selectively indexing said feeder box with said

assemblies therein with a lineal indexing movement transversely of its length and to the path of movement of said weft or filling threads to any one of a plurality of indexed positions, means for actuating one of said assemblies in each indexed position longitudinally to feed and transfer the thread correlated thereto to a shuttle, and means locking the remaining assemblies in each indexed position against longitudinal movement.

2. In a weaving machine of the gripper shuttle type as defined in claim 1 and wherein the means for selectively indexing said feeder box with said assemblies therein includes an indexing mechanism operatively connected to said feeder box, and a selecting or pattern mechanism driven in timed relationship to the operation of the weaving machine and operatively connected to said indexing mechanism for actuating the latter to effect selective indexing of said feeder box and selective feeding and transferring of the weft or filling threads to the shuttles.

3. In a weaving machine of the gripper shuttle type as defined in claim 1 and wherein there is provided tensioning means for the weft or filling threads and which includes an indexible member operatively connected to said feeder box to be indexed in correlation to the indexing of the feeder box, separate tensioning rods for each thread, means operative in each indexed position of the feeder box for moving the tensioning rod for the thread that is currently being fed and transferred to a shuttle to a non-tensioning position and then to a tensioning position and means for maintaining the other tensioning rods in thread tensioning position while said one tensioning rod is being actuated to non-tensioning position and back to tensioning position.

4. In a weaving machine of the gripper shuttle type as defined in claim 1 and wherein a separate brake mechanism and a separate drag mechanism are provided for each weft or filling thread, together with means operating in correlation to the indexing movements of the feeder box for releasing and then reapplying the brake mechanism and drag mechanism for the one weft or filling thread that is being picked through the shed for each indexed position of the feeder box while the brake and drag mechanisms for the other weft or filling threads are maintained applied.

5. In a weaving machine of the gripper shuttle type as defined in claim 1 and wherein the means for actuating one of said feeding and gripping assemblies in each indexed position of the feeder box moves said one assembly longitudinally of the feeder box from an index position to a transfer position to feed and transfer its correlated thread which it is gripping to a shuttle and then follows the shuttle to a pick up position wherein it regrips its correlated thread and returns to index position.

6. In a weaving machine of the gripper shuttle type as defined in claim 1 and wherein there is provided pick-back mechanism for effecting one pick-back operation at a time and which pick-back mechanism includes means preventing the initiation of the pick-back operation during the indexing of said feeder box.

7. In a weaving machine of the gripper shuttle type, a weft or filling thread selecting mechanism comprising a feeder box containing in side by side relationship a plurality of weft thread feeding and gripping assemblies and each correlated to one of the weft or filling threads; means for selectively indexing said feeder box with said assemblies therein by linear movements transversely of said box to any one of a plurality of indexed positions and including an indexing cam driven in timed relationship to the operation of the machine, an indexer bar operatively connected to said feeder box, and means for operatively interconnecting said indexing cam and said indexer bar to effect selective predetermined indexing movements of said bar and said feeder box; means for actuating one of said assemblies in each indexed position of said feeder box linearly and longitudinally of the feeder box to feed and transfer to a shuttle the thread

correlated to said one assembly; and means locking the remaining assemblies in each indexed position of the feeder box against longitudinal movement.

8. In a weaving machine of the gripper shuttle type as defined in claim 7 and wherein said indexing cam is provided with a plurality of axially spaced peripheral camming grooves while the means for operatively interconnecting said indexer bar and said indexing cam to effect indexing movements of the bar and said feeder box includes cam follower pins carried by said bar and each correlated to a camming groove in said indexing cam, and means is provided for selectively inserting said pins into their respective camming grooves one at a time to effect the selective predetermined indexing movements for said bar and said feeder box.

9. In a weaving machine of the gripper shuttle type as defined in claim 8 and wherein each of said camming grooves in said indexing cam includes a wide non-camming portion, a narrow non-camming portion, and a 20 tapered funnel-like camming portion interconnecting said wide and narrow portions.

10. In a weaving machine of the gripper shuttle type, a weft or filling thread selecting mechanism comprising a feeder box containing in side by side relationship a 25 plurality of thread feeding and gripping assemblies each correlated to one of the weft or filling threads; means for selectively indexing said feeder box with said assemblies to any one of a plurality of indexed positions and including an indexing cam rotated in timed relationship to the operation of the machine and provided with axially spaced peripheral camming grooves, certain of said camming grooves being provided with camming wall surfaces disposed to effect camming action in opposite directions and other of said camming grooves being provided with 30 a single camming wall surface for effecting camming action in a single direction; an indexer bar operatively connected to said feeder box and longitudinally movable in opposite directions and provided with longitudinally spaced cam following pins corresponding in number to 35 said camming grooves; and means operating in timed relationship to the operation of the machine for automatically inserting one of said cam following pins at a time into its correlated camming groove in said indexing cam to effect predetermined indexing movement of said bar and said feeder box; means for actuating one of said 40 assemblies in each indexed position of said feeder box longitudinally of the feeder box to feed and transfer the thread correlated thereto to a shuttle; and means locking the remaining assemblies in each indexed position of the 45 feeder box against longitudinal movement.

11. In a weaving machine of the gripper shuttle type, a weft or filling thread selecting mechanism comprising a feeder box containing in side by side relationship a plurality of longitudinally movable thread feeding and 50 gripping assemblies each correlated to one of the weft or filling threads; indexing mechanism for selectively indexing said feeder box with said assemblies thereto to any one of a plurality of indexed positions and including a longitudinally movable indexer bar operatively connected to said feeder box, an indexing cam rotated in timed relationship to the operation of the machine and provided with axially spaced peripheral camming grooves, cam following pins slidably carried by said indexer bar and correlated to said camming grooves to be inserted therein, 55 spring means normally maintaining said pins retracted from said grooves, plungers cooperating with said cam following pins to move the same against the action of said spring means, separate means for actuating each of said plungers, and means for actuating said separate means selectively and including a selecting or pattern mechanism driven in timed relation with the machine, and separate operative connections between said selecting or pattern mechanism and each of said separate means whereby said selecting or pattern mechanism automatically and selectively effects selective insertion of said 60 70 75

cam following pins into their correlated camming grooves one at a time to produce predetermined indexing of said bar and said feeder box; means for actuating one of said assemblies in each indexed position of said feeder box longitudinally of the feeder box to feed and transfer the thread correlated thereto to a shuttle; and means locking the remaining assemblies in each indexed position of the feeder box against longitudinal movement.

12. In a weaving machine of the gripper shuttle type as defined in claim 11 and wherein said separate means for actuating said plungers are rockable bell cranks having one arm operatively associated with said plungers and the other arm operatively connected to the said separate operative connections between said selecting and pattern mechanism and said separate means.

13. In a weaving machine of the gripper shuttle type as defined in claim 11 and wherein said selecting or pattern mechanism includes a pattern chain provided with predeterminedly arranged actuating rollers, while said separate operative connections include a plurality of bell crank levers rockably mounted in side by side relationship and having arms overlying said pattern chain to be engaged and moved by said actuating rollers and other arms operatively connected to actuating rods which in turn are operatively connected to said separate means.

14. In a weaving machine of the gripper shuttle type as defined in claim 11 and wherein said indexing mechanism includes means for locking said indexer bar and said feeder box against movement during a portion of each rotation of said indexing cam and for releasing said indexer bar during another portion of each rotation of said indexing cam so indexing movement can be imparted to said bar and said feeder box.

15. In a weaving machine of the gripper shuttle type as defined in claim 14 and wherein said means for locking said indexer bar includes a member rotating with said indexing cam.

16. In a weaving machine of the gripper shuttle type as defined in claim 15 and wherein said member rotatable with said indexing cam is a disk provided with a circumferential cutout recess of an angular extent corresponding to the indexing portion of each rotation of said indexing cam, while said indexer bar is provided with locking grooves spaced apart longitudinally of said bar a distance equal to one step of indexing movement of said bar, said disk in each rotation of said indexing cam engaging in one of said grooves to lock said bar against indexing movement during the non-indexing portion of the rotation of said indexing cam while the circumferential recess in said disk overlies said groove during the indexing portion of rotation of said cam whereby said bar is free to have indexing movement imparted thereto.

17. In a weaving machine of the gripper shuttle type as defined in claim 15 and wherein said member that rotates with said indexing cam is a locking cam, while said bar is provided with locking notches spaced apart longitudinally of the bar a distance equal to one step of indexing movement, and a locking plunger is provided engageable with said notches while operative connections extend between said plunger and said locking cam such that said plunger is retracted with respect to said notches during the indexing portion of rotation of said indexing cam and is in locking relationship relative to said notches during the remaining and non-indexing portion of rotation of said indexing cam.

18. In a weaving machine of the gripper shuttle type, a weft or filling thread selecting mechanism comprising a feeder box containing in side by side relationship a plurality of longitudinally moving feeding and gripping assemblies each correlated to a separate weft or filling thread, indexing mechanism for selectively indexing said feeder box with said assemblies therein transversely to the path of movement of said weft or filling threads to any one of a plurality of indexed positions, means for actuating one of said assemblies in each indexed position longi-

tudinally to feed and transfer the thread correlated thereto to a shuttle, and means locking the remaining assemblies in each indexed position against longitudinal movement; said indexing mechanism including a shaft rotatable in timed relation to the operation of the machine, an indexing cam freely rotatable on said shaft and provided with a first clutch element, a clutch member splined on said shaft and provided with a second clutch element coacting with said first clutch element, and spring means normally maintaining said clutch elements in engaged relationship whereby said indexing cam rotates with said shaft.

19. In a weaving machine of the gripper shuttle type as defined in claim 18 and wherein said indexing cam is provided with a plurality of axially spaced camming grooves extending partially around the periphery of said cam while said indexing mechanism further includes a longitudinally indexable indexer bar operatively connected to said feeder box and provided with longitudinally spaced transversely slidable cam following pins adapted to be selectively inserted one at a time into said camming grooves to effect predetermined indexing movement of said bar and feeder box.

20. In a weaving machine of the gripper shuttle type as defined in claim 18 and wherein there is included a master stop rod which when actuated stops the machine, while said indexing cam mounts a spring pressed plunger having an end normally located closely adjacent to a surface area on said clutch member when said clutch elements are engaged, said plunger having its opposite end provided with a laterally extending arm adapted when said clutch member is moved to clutch disengaged position and said plunger is moved thereby to abnormal position to effect actuation of the master stop rod to produce stopping of the operation of the machine.

21. In a weaving machine of the gripper shuttle type as defined in claim 19 and wherein each of said camming grooves in said indexing cam includes a wide non-camming portion of a width such that its cooperating cam following pin can be inserted therein in any indexed position of the indexer bar, said camming grooves further including a narrow non-camming portion of such width as just to receive its cooperating cam following pin, and a tapered funnel-like camming portion interconnecting said wide and narrow portions.

22. In a weaving machine of the gripper shuttle type as defined in claim 21 and wherein the tapered funnel-like camming portions of certain of said camming grooves have a straight side wall and an inclined side wall while the camming portions of other of said camming grooves have both side walls inclined.

23. In a weaving machine of the gripper shuttle type as defined in claim 21 and wherein certain of the inclined side walls of the tapered funnel-like camming portions of said camming grooves are formed to act on their cam following pins to impart one or more steps of indexing movement to said indexer bar depending on whether their camming pins engage said inclined side walls for a portion of their length or for their entire length, while other of said inclined side walls of said tapered funnel-like camming portions of said camming grooves are disposed so as to impart single step indexing movement of said indexer bar when engaged by their cam following pins.

24. In a weaving machine of the gripper shuttle type, a weft or filling thread selecting mechanism comprising a feeder box containing in side by side relationship a plurality of feeding and gripping assemblies each correlated to a separate weft or filling thread and movable longitudinally of said feeder box, means for selectively indexing said feeder box with said assemblies therein transversely to the path of movement of said weft or filling threads to any one of a plurality of indexed positions, means for actuating one of said assemblies in each indexed position longitudinally to feed and transfer the thread correlated thereto to a shuttle, and means locking

the remaining assemblies in each indexed position against longitudinal movement; each of said assemblies having an upwardly extending portion located beyond one end of said feeder box and provided in its upper edge with a recess, said means for locking the remaining assemblies in each indexed position against longitudinal movement including longitudinally aligned fixed locking bars having their inner or adjacent ends spaced apart to form a slot which overlies the said recess in said one of said assemblies in each indexed position of the feeder box, said lock bars extending through the said recesses in the remaining assemblies in each indexed position, while said means for actuating one of said assemblies in each indexed position includes a lug extending through said slot and into the recess of said one assembly.

25. In a weaving machine of the gripper shuttle type as defined in claim 24 and wherein each of said assemblies at the end thereof where the upwardly extending portion is located is provided with spring arms extending beyond said portion and having gripping jaws on their extending ends adapted when closed to grip a weft or filling thread and when open to release the same.

26. In a weaving machine of the gripper shuttle type, a weft or filling thread selecting mechanism comprising a feeder box containing in side by side relationship a plurality of feeding and gripping assemblies each correlated to a separate weft or filling thread and movable longitudinally of said feeder box and having their thread gripping ends extending outwardly of one end of said feeder box, means for selectively indexing said feeder box with said assemblies therein transversely to the path of movement of said weft or filling threads to any one of a plurality of indexed positions, means for actuating one of said assemblies in each indexed position longitudinally to feed and transfer the thread correlated thereto to a shuttle, means adjacent said one end of said feeder box for locking the remaining assemblies in each indexed position against longitudinal movement, and a thread tensioning mechanism located adjacent the other end of said feeder box and including separate thread tensioning rods for each weft or filling thread, and means indexable in correlation to the indexing movements of said feeder box for effecting selective actuation in each indexed position of the feeder box of one of said tensioning rods from thread tensioning position to a released non-tensioning position and back to thread tensioning position while the remainder of said tensioning rods are maintained in thread tensioning position.

27. In a weaving machine of the gripper shuttle type as defined in claim 26 and wherein the machine is provided with an upper cam shaft, spaced cams rotatable by said upper cam shaft, a rockable shaft, and operative connections between said rockable shaft and said spaced cam whereby rotation of said upper cam shaft effects rocking movement of said rockable shaft, while said thread tensioning mechanism includes an oscillatable arm operatively connected to said rockable shaft and to means which is operatively connected to said one of said tensioning rods in each indexed position of said feeder box.

28. In a weaving machine of the gripper shuttle type as defined in claim 27 and wherein each of said tensioning rods at one end thereof is provided with an actuating shoe having a recess therein, while said means for operatively connecting said oscillatable arm to said one tensioning rod in each indexed position of the feeder box includes a link pivotally connected to said oscillatable arm and to a slide provided with a post which interfits the recess in the actuating shoe of said one tensioning rod.

29. In a weaving machine of the gripper shuttle type, a weft or filling thread selecting mechanism comprising a feeder box containing in side by side relationship a plurality of feeding and gripping assemblies each correlated to a separate weft or filling thread and movable longitudinally of said feeder box, means for selectively

indexing said feeder box with said assemblies therein transversely to the path of movement of said weft or filling threads to any one of a plurality of indexed positions, means for actuating one of said assemblies in each indexed position longitudinally to feed and transfer the thread correlated thereto to a shuttle, means locking the remaining assemblies in each indexed position against longitudinal movement; and thread tensioning mechanism including a tensioning rod supporting block provided with a plurality of guides spaced apart and correlated to said assemblies and to the threads, a thread tensioning rod in each of said guides, operative connections between said supporting block and said feeder box for indexing said supporting block in correlation to the indexing of said feeder box, a stationary support provided at its upper end with a supporting surface and with a vertically extending slot which in each indexed position of said feeder box and said block aligns with the lower end of one of said tensioning rods while the lower ends of the remaining tensioning rods are supported on said supporting surface to maintain the same in raised thread tensioning position, and means operating in timed relation with the machine and acting to move said one tensioning rod downwardly in said slot to non-tensioning position and then upwardly therein to tensioning position.

30. In a weaving machine of the gripper shuttle type, a weft or filling thread selecting mechanism comprising a feeder box containing in side by side relationship a plurality of feeding and gripping assemblies each correlated to separate weft or filling threads and movable longitudinally of said feeder box, means for selectively indexing said feeder box with said assemblies therein transversely to the path of movement of said weft or filling threads to any one of a plurality of indexed positions, means for actuating one of said assemblies in each indexed position longitudinally to feed and transfer the thread correlated thereto to a shuttle, means locking the remaining assemblies in each indexed position against longitudinal movement; and thread tensioning mechanism including a stationary support provided with a plurality of guides for a plurality of tensioning rods corresponding in number to said assemblies and spaced apart transversely of said support a distance equal to one step of indexing movement of said feeder box, thread tensioning rods slideable in said guides and provided on their lower ends with actuating shoes having recesses therein, said stationary support being provided with guideways in which said actuating shoes can slide, a member extending transversely of said stationary support and slidably mounted thereon and provided with a base having a slot therein adapted to align with one of said guideways, operative connections between said member and said feeder box for indexing said member in correlation to the indexing movements of said feeder box, the slot in said base of said member aligning with the recess in the actuating shoe of one of said tensioner rods in each indexed position of said member while said base extends through the recesses in the actuating shoes of the remainder of said tensioner rods and acts to maintain the remainder of said tensioner rods in raised thread tensioning position, and oscillating means operating in timed relation with the machine and having an element operatively associated therewith which extends through said slot in said base of said indexable member and into the recess in the actuating shoe of said one tensioner rod in each indexed position of said member and acting to move said one tensioning rod and its actuating shoe downwardly in said guideway to non-tensioning position and then upwardly therein to tensioning position.

31. In a weaving machine of the gripper shuttle type, a weft or filling thread selecting mechanism comprising a feeder box containing in side by side relationship a plurality of feeding and gripping assemblies each correlated to a separate weft or filling thread and indi-

vidually movable linearly and longitudinally of said feeder box, means for selectively indexing said feeder box with said assemblies therein linearly and transversely of its length and to the path of movement of said weft or filling threads to any one of a plurality of indexed positions, means for actuating one of said assemblies in each indexed position longitudinally to feed and transfer the thread correlated thereto to a shuttle, means locking the remaining assemblies in each indexed position against longitudinal movement, separate brake and drag mechanisms for each weft or filling thread and including separate pivoted releasing arms for each brake and drag mechanism, separate members for selectively actuating the drag releasing arms and the brake releasing arms, said members being mounted for rocking indexing movement and for axial arm actuating movement, means operatively interconnecting said members with said feeder box to produce indexing movement of said members in correlation to the indexing movement of said feeder box, and means acting in timed relationship to the operation of the machine for effecting axial movement of said members after each indexing movement thereof to effect actuation of the drag and brake releasing arms for the one weft or filling thread that is currently being picked through the shed.

32. In a weaving machine of the gripper shuttle type as defined in claim 31 and wherein said members include rockable and axially movable hubs provided with actuating portions having thereon spaced substantially arcuately arranged series of actuating screws, one of which screws on each actuating portion is aligned with a cooperating abutment member carried by one of said brake releasing arms and one of said drag releasing arms in each indexed position of said feeder box and said members whereby when said members are moved axially said one screw on each actuating portion will engage the abutment element of a predetermined releasing arm to move said arm in releasing direction.

33. In a weaving machine of the gripper shuttle type as defined in claim 31 and wherein there is an upper cam shaft driven in timed relation to the operation of the machine and provided with a pair of axially spaced cams, while the means for moving said members axially includes a pair of rockable bell cranks, separate plungers operatively associated respectively with said cams and each engaging one of the arms of said bell cranks, push rods operatively associated with the other arm of said bell cranks and with rockable lifter elements having lifting portions underlying cooperating portions on said members whereby rocking movements of said elements effected through said cams, plungers, bell cranks and push rods move said members axially.

34. In a weaving machine of the gripper shuttle type, a weft or filling thread selecting mechanism comprising a feeder box containing in side by side relationship a plurality of feeding and gripping assemblies each correlated to a separate weft or filling thread and independently movable linearly and longitudinally of said feeder box, means for selectively indexing said feeder box with said assemblies therein linearly and transversely of its length and to the path of movement of said weft or filling threads to any one of a plurality of indexed positions, means locking all but one of said assemblies against longitudinal movement in each indexed position of said feeder box; and means for actuating said one of said assemblies in each indexed position longitudinally to feed and transfer the thread correlated thereto to a shuttle and including an upper cam shaft driven in timed relation to the operation of the machine, an oscillatable feeder arm operatively connected to said one assembly in each indexed position, operative connections between said upper cam shaft and said feeder arm for oscillating the latter, said feeder arm moving said one assembly from index position to transfer position wherein the thread is transferred from said

one assembly to the shuttle and then to pick-up position and back to indexing position.

35. In a weaving machine of the gripper shuttle type as defined in claim 34 and wherein separate stationary abutment means are provided engageable with said feeder arm in index and pick-up positions, respectively, of said one assembly while a movable stop rod is provided and driven in timed relation to the operation of the machine to be located momentarily in the path of movement of said one assembly when the latter is in transfer position.

36. In a weaving machine of the gripper shuttle type, a weft or filling thread selecting mechanism comprising a feeder box containing in side by side relationship a plurality of feeding and gripping assemblies each correlated to a separate weft or filling thread and movable longitudinally of said feeder box outwardly of one end of the latter, means for selectively indexing said feeder box with said assemblies therein transversely of its length and to the path of movement of said weft or filling threads to any one of a plurality of indexed positions, means for actuating one of said assemblies in each indexed position longitudinally to feed and transfer the thread correlated thereto to a shuttle, means locking the remaining assemblies in each indexed position against longitudinal movement, tensioning mechanism for the weft or filling threads and including a separate tensioning rod for each thread, means operative in each indexed position of the feeder box for moving the tensioning rod for the thread that is currently being fed and transferred to a shuttle to a non-tensioning position and then to a tensioning position, and means for maintaining the other tensioning rods in thread tensioning position; and a thread detector mechanism including a detector rod underlying all of said threads and contacting the thread that is currently being fed and transferred when its tensioning rod is in non-tensioning position, said detector rod being carried by a rocking detector shaft normally urged in detecting direction and operatively associated with the master stop rod of the machine, said detector rod being located intermediate said feeder box and said tensioning mechanism.

37. In a weaving machine of the gripper shuttle type, a main shaft, a cross shaft driven by said main shaft, an indexing mechanism including a rotatable indexing cam, operative connections between said cross shaft and said indexing cam for rotating the latter only in a forward direction, a feeder box containing in side by side relationship a plurality of feeding and gripping assemblies each correlated to a separate weft or filling thread and movable longitudinally of said feeder box, operative connections between said indexing mechanism and said feeder box for indexing the latter transversely of its length and to the path of movement of said weft or filling threads to any one of a plurality of indexed positions, a selecting or pattern mechanism operatively connected with said indexing mechanism to effect selective actuation thereof and driven in a forward direction from said cross shaft; and a pick-back mechanism for driving said selecting or pattern mechanism in the reverse direction for one pick-back operation and including a rotatable shaft normally rotating in a forward direction but during a pick-back operation rotating in a reverse direction, a pick-back control shaft manually movable in one direction to initiate a pick-back operation, and cooperating means carried by said rotatable shaft and said pick-back control shaft and engageable during the indexing portion of the rotation of said indexing cam to prevent manual movement of said pick-back control shaft to initiate a pick-back operation.

38. In a weaving machine of the gripper shuttle type as defined in claim 37 and wherein the cooperating means on said rotatable shaft and said pick-back control shaft include a collar fixed to said rotatable shaft and provided

with a locking portion and a locking bar carried by said pick-back control shaft and provided with a locking recess in which said locking portion of said collar is located during the indexing portion of rotation of the indexing cam.

39. In a weaving machine of the gripper shuttle type as defined in claim 38 and wherein said locking bar is pivotally mounted on a block secured eccentrically to said pick-back control shaft, said block being provided with a shoulder, spring means acting on said locking bar to normally hold it engaged with said shoulder, said locking bar being capable of swinging movement away from said shoulder and against the action of said spring means.
